MARC STERN, OF DETROIT, MICHIGAN, ASSIGNOR TO DOEHLER DIE-CASTING CO., A CORPORATION OF NEW YORK.

DIE-CASTING MACHINE.

Application filed May 24, 1924. Serial No. 715,712.

My invention relates to die casting machines, and general objects of my invention are to reduce the cost of making die castings and to improve the quality thereof. More particular objects are to increase the output of a die casting machine and to reduce the amount of manual attention and manipulation required to a minimum. In this connection, the main object of my invention is 10 to produce a completely automatic die casting machine, that is to say, a die casting machine which will perform automatically in proper sequence, or concomitantly, a series or a plurality, of operations forming a complete cycle in the complete casting operation. Other objects and advantages of my invention will hereinafter appear.

Commonly heretofore die casting machines have only been partly automatic or 20 semi-automatic, requiring both constant attention during a casting operation and several manipulations to be performed at intermediate stages thereof. For example, commonly, in such semi-automatic machines, 25 one manipulation is required to cause the die to be closed and clamped to the nozzle of the pressure chamber or casting pot, another manipulation to cause the molten metal to be forced into the die, another manipulation (after an estimated interval of 30 time to permit the casting to harden) to cause the pressure to be released in the casting pot, and another manipulation to cause the die to be unclamped from the nozzle 35 and opened; and commonly also several additional manipulations are required. Upon starting the machine of my present invention, all its operations are initiated and performed automatically; such operations including the closing of the die and its clamping to the nozzle, provision being made for a die-charging period of rest of the die in its closed and clamped condition, the applying of pressure to the molten metal in the 40 pressure chamber to force it into the die and hold it there, the releasing of the pressure in the pressure chamber, the unclamping and opening of the die, the withdrawing of cores from the casting, and the ejecting of the 45 casting from the die to deliver it from the machine; and further including the feeding of ingots to the pressure chamber (which in

the machine of my invention is also a melting pot) to replenish the metal therein.

My invention includes, in combination, 55 mechanisms and devices adapted and arranged to initiate and perform all operations automatically. My invention also includes various features of construction and combinations of parts as will appear from the 60 following description.

I shall now describe the die casting machine embodying my invention illustrated in the accompanying drawings and shall thereafter point out my invention in claims. 65

Figure 1 is a front side elevation of a complete die casting machine embodying my invention, as it appears at rest in the idle condition, the lower part of a supporting standard being broken away. 70

Figure 2 is a partial transverse section of the machine taken on the staggered line 2—2 of Fig. 1, showing in elevation the lower part of the furnace, the air pipes, and the valves in control of the supply of compressed air for the pressure chamber or casting pot. 75

Figure 2^a is a partial vertical section taken on the line 2^a—2^a of Fig. 2, showing in end elevation the air-controlling valve appearing at the left in Fig. 2. 80

Figure 3 is an inclined plan view on an enlarged scale of the left end of the machine as shown in Fig. 1, but with the machine in operation, showing the die sections in their die casting position of rest, just prior to the admission of compressed air into the pressure chamber to force the molten metal into the die. 85

Figure 4 is a similar further enlarged view of what appears at the left in Fig. 3, showing a succeeding phase of operation of some of the controlling devices, after the molten metal has been forced into the die and the opening movement of the die initiated. 90

Figure 5 is an enlarged detached view in elevation of a controlling device forming a part of the metal-replenishing feed mechanism appearing in Fig. 1 and showing that an ingot will be fed at the next casting operation, the parts being positioned to correspond to Fig. 1, in which the die is open and retracted. 100

Figure 6 is a similar view, partly broken away, and showing the next succeeding casting operation as taking place, as in Fig. 3, at which an ingot will be fed when the die is retracted.

Figure 7 is a transverse section, more enlarged than Fig. 3 and taken on line 7—7 of Figs. 1 and 3, as seen in Fig. 1, but with the operating parts in the position shown in Fig. 3.

Figure 8 is a partial vertical longitudinal section, somewhat less enlarged than Fig. 7, taken on line 8—8 of Figs. 3, 7 and 9, showing in section a reversing gearing and its clutch, and showing other parts in elevation, including a one-revolution clutch and devices operated thereby, the operating parts being in the position shown in Fig. 3.

Figure 9 is a transverse section taken on line 9—9 of Figs. 1, 3 and 8, showing the one-revolution clutch and its adjuncts in section and other parts in elevation, the operating parts being in the position shown in Figs. 3 and 8.

Figure 10 is a partial transverse section taken on line 10—10 of Fig. 8, showing the one-revolution clutch and its adjuncts in elevation.

Figure 11 is a greatly enlarged transverse section taken on line 11—11 of Fig. 1, showing the inner or gated die section in face view, its die carrier appearing in elevation.

Figure 12 is a further enlarged transverse section taken on line 12—12 of Figs. 3 and 13, and is more particularly illustrative of the devices for withdrawing the cores and for ejecting the castings, these devices being carried by the second or outer die carrier; this figure also showing, in broken lines, additional core-pulling means to be provided if needed.

Figure 13 is a vertical longitudinal section taken on the staggered line 13—13 of Figs. 3 and 12, drawn to the scale of Fig. 12.

Figure 14 is a partial transverse section between the faces of the die sections, taken on line 14—14 of Fig. 13, and shows in elevation the face of the outer or second die section.

Figure 15 is a partial longitudinal section looking downward from line 15—15 of Figs. 13 and 14, including both die sections.

Figure 16 is a partial vertical longitudinal section taken on line 16—16 of Figs. 14 and 15, as viewed in Fig. 14.

Figure 17 is a longitudinal section as viewed from above and taken on line 17—17 of Figs. 1, 12 and 13, the outer die section having been separated from the inner die section, which latter does not appear in Fig. 17, also the cores having been withdrawn and the ejector pins projected, as in Fig. 1; Fig. 17 also showing, in broken lines, the additional core-pulling means appearing in Fig. 12.

Figure 18 is a further enlarged partial vertical longitudinal section similar to Fig. 13, showing the die as having been filled with molten metal to form a casting.

Figure 19 is an enlarged elevation of the completed casting, as it would appear when viewed from the left in Fig. 18.

Figure 20 is a similar view as viewed from the left in Fig. 19 and from the rear in Fig. 18.

The automatically operated metal replenishing feed mechanism, for feeding ingots to the combined melting pot and casting pot or pressure chamber, illustrated in the accompanying drawings, and described and claimed herein as a feature of the die casting machine of my present invention, is in some respects and generally similar to that forming the subject of the application for patent of Charles Pack for die casting apparatus filed October 27, 1923, Serial No. 671,084 (Patent No. 1,592,125, dated July 13, 1926) and containing the broader claims for such mechanism: also the parts of the machine for supporting the die sections and for moving them relatively to each other, shown in the drawings, and described and claimed herein as a feature of my present invention, are of a construction substantially the same as that shown and described, but not claimed, in the above noted patent of Pack.

In the die casting machine illustrated in the accompanying drawings as an embodiment of my invention, a fire box or furnace 1, mounted upon a base 2, is provided with an inclined cover plate 3, secured thereon, for example, by means of bolts, as shown. The interior of the furnace may be heated to the desired temperature by any suitable means, for example, by means of commonly employed gas burners (not shown). A vertically elongated melting pot 4, for the metal to be cast and which also constitutes a casting pot or pressure chamber, is supported by the cover 3 and extends for the most part down into the furnace but at its upper end projects above the cover 3 and is provided with a cover cap 5. The combined pressure chamber and melting pot 4, which is generally of tea-pot shape, has an inclined delivery spout 6 extending upwardly and outwardly from adjacent its bottom and at its upper end at the outside of the cover 3 is provided with an inclined outwardly and upwardly projecting discharge nozzle 7. Suitable means, such as adjusting screws, may be provided for adjusting the position of the pressure chamber 4 on the cover 3, thereby to adjust the nozzle 7 to assure its alignment with the gate of the die, one such adjusting screw 8 being shown in Figure 1, and there may be as many such screws and variously located as desired around the flange 9 of the pressure chamber, which flange rests upon and may be further secured to the

cover plate 3. In order to provide for easily lifting or removing the cover 3 and parts mounted thereon, counterbalancing weights 10 are hung to a cable 11 which passes over 5 a pulley 11^a and is secured to the upper edge of the cover plate 3. The inclination of the nozzle 7 and spout 6 provides for the draining of the molten metal from the nozzle 7 back into the pressure chamber 4 at the end 10 of each casting operation.

The pressure-applying means for forcing out the molten metal from the pressure chamber 4 through its nozzle 7 into the die will now be described, and in carrying out 15 my invention, a suitable pressure fluid, such as compressed air, is employed for this purpose. The metal-containing main body part of the combined melting pot and casting pot or pressure chamber 4 is contained within 20 in the furnace 1 so as to be fully exposed to the heat therein, but at its upper end, which projects to the outside of the cover 3, the pressure chamber 4 has an interiorly reduced portion forming a small air chamber 25 12, it being desirable, both for economy and for speed of operation, that the amount of pressure fluid used at each casting operation shall be reduced to a minimum. In this 30 connection it is also to be noted that the comparatively small transverse or horizontal cross-sectional area of the vertically elongated pressure chamber 4 not only contributes to these desirable results but also results in only a small surface of molten 35 metal to be exposed to the air, thereby reducing the formation of oxides and other dross. The compressed air, or other suitable pressure fluid, is admitted into and permitted to exhaust from the pressure chamber 4 40 through a pipe 13 connected to the upper end of the reduced portion 12 of the pressure chamber 4.

Automatically operated means are provided for controlling the pressure fluid, such 45 means including a valve device 14, which will now be described. Any suitable valve mechanism may be provided for controlling the pressure fluid, and the valve device 14 is a substantially usual form of three-way 50 valve, which, for the sake of brevity, need not be illustrated or described as to all of its details. A supply pipe 15 is connected to the inlet port of the valve device 14, the delivery port of the latter is connected to the 55 pipe 13 leading to the pressure chamber 4, and the exhaust port thereof has connected thereto an exhaust pipe 16 which may open to the atmosphere. The valve device 14 has a 60 depressible valve stem 17 which is normally held at its upper position, or returned thereto, by a coiled thrust spring 18. The valve stem 17 may be depressed by means of a 65 small lever 19, of the first order, pivoted upon the valve body or casing. The construction and arrangement are such that

when the valve stem 17 is in the raised position shown in the drawings (Figs. 1, 2 and 2^a), the valve is closed, so that pressure fluid cannot pass from the supply pipe 15 through the valve device 14; and the pressure chamber pipe 13 is in communication, through the valve device, with the exhaust pipe 16, so that there will be no fluid pressure upon the molten metal in the pressure chamber 4. When the valve stem 17 is depressed, by lifting the outer end of the valve lever 19, the exhaust port, connected to the exhaust pipe 16, is closed and the supply pipe 15 is placed in communication, through the valve device, with the pressure chamber pipe 13, thereby admitting pressure fluid into the pressure chamber 4 to force the molten metal therefrom into the die. The means for automatically operating the valve device 14, to admit pressure fluid into or exhaust it from the pressure chamber 4, will be described hereinafter. A main supply pipe 20, which may be connected to any suitable source of pressure fluid, is adapted to communicate with the secondary supply pipe 15 through the intermediary of a second valve device 21 forming a part of an automatically operated safety device to be hereinafter described and its purpose explained. 95

The die comprises two movable parts or sections 22 and 23, of a suitable contour on their inner faces so as, when closed together, to form between them the die chamber or die cavity 24, (Figs. 11, 13, 14, 15, 16 and 18), the shape of this cavity determining the shape of the casting, the die shown in the drawings being adapted to produce the casting shown in Figs. 19 and 20 and referred to hereinafter. The first or 100 inner die section 22 has centrally therethrough an inlet port or gate 25 communicating with the die cavity 24 and terminating outwardly at the back of the die section in a recess 26 adapted to fit snugly 105 over the end of the nozzle 7 when the die sections are closed together and brought to the casting position, as shown in Figs. 13 and 18. 110

The means for supporting the die sections 22 and 23 and for moving them relatively to each other and to the nozzle 7 will now be described; according to my invention, automatically acting mechanism, hereinafter to be described, being provided for 115 moving the die sections through a complete cycle, to and from the casting position, and adapted to provide a die-charging period of rest of the die sections at the casting position. 120

A pair of inclined, strong parallel supporting and guide rods 27 extend laterally outwardly and upwardly from the furnace 1. At their lower or inner ends the rods 27 are secured to the furnace 1 by means 130

of a cross bar 28 bolted to the furnace 1 below the nozzle 7 and which is further supported and secured to the furnace by means of a pair of diagonal side rods 29 (Figs. 1, 2 and 3). The outer raised ends of the rods 27 are supported by means of brackets 30 upon the upper end of a supporting standard 31. Mounted upon the outer end portions of the rods 27 and adjustable longitudinally thereof is a mechanism-carrying frame or machine head 32. For effecting adjustment of the frame 32, internally threaded worm wheels 33 are mounted to travel along screw-threaded portions of the rods 27 between shoulder-forming portions of the frame 32 and shoulders formed by the rod-encircling ends of a transverse frame piece 34 bolted to the frame 32 to form a part thereof, the worm wheels 33 being engaged by worms 35 fixed on a transverse shaft 36 journaled in the ends of the frame piece 34 and having a squared end 37 for the application of a crank (Figs. 1, 3, 8 and 9). The frame 32 may be fixed in adjusted position by means of clamp nuts 38 on the rods 27 at the inner end of the frame. The above described adjusting means for the frame 32 provides for adjusting the inner die section 22 relatively to the nozzle 7, as will hereinafter appear.

The construction provided, as a part of my present invention, for supporting the die sections 22 and 23 and for moving them relatively to each other, and now to be described, is similar to that disclosed in the hereinbefore mentioned Pack patent. The inner die section 22, which is next to the nozzle 7, is supported by a first or inner die carrier 39, being secured to the outer side thereof from the nozzle 7, this die carrier having through it a central opening 40 large enough to receive freely the nozzle 7. The die carrier 39 is slidably mounted upon the rods 27, which form a guideway therefor and maintain the gate 25 of the die section 22 in alignment with the discharge port 41 of the nozzle 7. A plate-like die-carrier-operating member 42, forming a cross-head, is slidably mounted upon the rods 27 next to the frame part 32 and is rigidly connected to the die carrier 39 by four parallel guide rods 43. Outward from the first die carrier 39 from the nozzle 7 and slidably mounted on the guide rods 43, which form a guideway therefor, is a second or outer die carrier 44, for the second or outer die section 23, which is supported thereon, at the inner side thereof, through the intermediary of an interposed U-shaped block 45 secured at its closed end to the die carrier 44, and a backing plate 46 secured to the open end of the block 45 and to which the die section 23 is secured (Figs. 1, 3, 12, 13 and 17), the interposed block 45 and plate 46 providing for the accommodation

of parts of automatically operated core-pulling and casting-ejecting devices to be hereinafter described.

In view of the fact that the inner die carrier 39, the slidable member or cross-head 42 and the connecting rods 43 form a rigid frame-work slidable as a unit, it is evident that by sliding the cross-head 42 in a forward direction, the inner die section 22 may be moved toward and clamped to the nozzle 7, and by sliding the cross-head 42 in the reverse or backward direction, the die section 22 will be retracted from the nozzle, and means involving my invention are to be hereinafter described for accomplishing this result. That part of the construction, hereinbefore referred to, for moving the die carriers, and hence the die sections, relatively to each other will now be described. Two pairs of toggle links each comprise two toggle links 47 and 48 pivoted together, the link 48 being considerably longer than the link 47 and being pivoted to the second or outer die carrier 44, while the shorter link 47 is pivoted to the slidable cross-head member 42, the two shorter links 47 being fixed, respectively, upon the ends of a short horizontal rock shaft 49 extending transversely to the path of movement of the cross-head 42 and journaled in bearing lugs 50 thereon. A spur gear 51, having a radius less than that of the shorter toggle links 47, is fixed upon the rock shaft 49 between the lugs 50 and at its lower side engages a stationary rack 52 carried by the central channel-shaped bar of a substantially I-shaped frame part 53 which at one of its ends is bolted to the inner end of the head or frame 32, and which at each of its ends is further supported upon the main supporting and guide rods 27 to partake of the sliding adjustment of the frame 32 thereon, hereinbefore described.

Upon movement being imparted to the first or inner die carrier 39, movement, in the same direction and at a multiplied rate, will be transmitted to the second or outer die carrier 44, through the coupling means including the toggle links 47 and 48 and the gear 51, these toggle links and the gear 51 forming operating means connecting together the two slidable die carriers 39 and 44 and the stationary frame 32, the outer die carrier 44 moving at a higher speed and through a greater distance than the inner die carrier 39, in the construction shown in the drawings, the outer die carrier 44 traveling, relatively to the nozzle 7, through about twice the distance traveled by the inner die carrier 39. The gear 51 in its travel along the rack 52 makes substantially a one-half rotation, so that when the die is open and retracted from the nozzle, as shown in Fig. 1, the shorter toggle links 47 will extend towards the frame 32, and when the die is closed and clamped to the nozzle, these short-

er toggle links will extend in the opposite direction or towards the die carriers, as shown in Fig. 3, so that the toggle is locked, thereby to lock or clamp the outer die section 23 firmly to the inner die section 22, the proportions and arrangement of the parts being such that this clamping together of the die sections takes place at the same time that the inner die section 22 is locked or 10 clamped to the nozzle 7 by its operating means, next to be described. The inner die carrier 39, together with its die section 22, may be adjusted relatively to the outer die carrier 44 and its die section 23, by means of 15 nuts 54 on extended threaded end portions of the connecting guide rods 43 at the cross-head 42. It will now be seen that when the cross-head 42 is moved in a forward direction the die sections will be closed together, 20 and when it is moved in the reverse or backward direction the die sections will be separated.

The operating means for imparting sliding movement to the die-carrier-operating member or cross-head 42, for thereby imparting concomitant sliding movement to the die carriers 39 and 44, forms a part of the hereinbefore mentioned automatically acting mechanism for moving the die sections through a complete cycle; as does also the above described means for moving the die sections relatively to each other. For sliding the cross-head 42, a second set of toggle links is provided, comprising two 35 pairs, each having two toggle links 55 and 56 pivoted together, the link 56 being considerably longer than the link 55 and being pivoted to the cross-head 42, the shorter link 55 being pivoted to the stationary frame 32, 40 the two shorter links 55 being fixed, respectively, upon the ends of a horizontal rock shaft 57, which extends transversely to the path of movement of the cross-head and is journaled in the forward end of the frame 32. Means, presently to be described, are 45 provided for automatically rocking the rock shaft 57 through substantially one-half rotations, first in a clockwise direction, as viewed in Fig. 1, and then, after a die-casting period of rest of the die at the 50 casting position, in a counter-clockwise direction. When the shaft 57 is thus rocked in the clockwise direction, it will turn the shorter toggle links 55 from their backwardly directed position shown in Fig. 1, in which the die section 22 is retracted 55 from the nozzle 7 and the die section 23 separated from the die section 22, to their forwardly directed position shown 60 in Fig. 3, in which the toggle is locked thereby to lock or clamp the inner die section 22 to the nozzle 7, also at the same time the outer die section 23 being locked or clamped to the inner die section 22, so that 65 the die will now be at the casting position, shown in Figs. 3, 13, 15, 16 and 18. It will now be clear that upon rocking the shaft 57 in the clockwise direction, the die carriers will be moved in the forward direction and relatively to each other and to the nozzle 70 to close the die and clamp it to the nozzle, and upon rocking this shaft in the opposite direction, the die carriers will be moved in the reverse or backward direction and relatively to each other and to the nozzle to 75 open the die and retract it from the nozzle. By adjusting the head or frame 32, as hereinbefore described, the inner die section 22 may be adjusted relatively to the nozzle 7, without thereby disturbing the hereinbefore 80 described adjustment of the die sections relatively to each other.

Means for automatically operating the above described operating means for the cross-head 42 and forming a part of the 85 complete automatically acting mechanism will now be described. A worm wheel 58, fixed medially on the cross-head operating rock shaft 57, is engaged by a worm 59 carried by the forward end of a reversible longitudinal shaft 60 journaled in the frame or head 32, it being evident that several rotations of the worm-carrying shaft 60 will be required, in one direction or the other, in order to impart the required half turn rotations in one direction or the other to the rock shaft 57. A short horizontal main drive shaft 61 is journaled in the back part of the frame 32 with its axis in the same plane as that of the reversible shaft 60, and at the back of the machine the projecting end of the drive shaft 61 has fixed thereon a driving pulley 62 which may be driven from any suitable source of power, such as a line shaft or an electric motor.

The drive shaft 61 may be connected to the reversible shaft 60 through the intermediary of reversing gearing, including a double clutch or reversing clutch. Such clutch may be of any suitable construction, and that employed in the present machine is of a well known construction, commonly used for various purposes and commonly known as the "Johnson" clutch, and which, therefore, has not been illustrated as to all its details. A bevel driving gear 63 fixed upon the inner end of the drive shaft 61 meshes at opposite sides with two aligned bevel gears 64 and 65 fixed, respectively, upon the hub portions of a pair of similar oppositely arranged cup-shaped clutch members 66 and 67 which are loosely mounted upon the reversible shaft 60 (Fig. 8), so that rotation of the drive shaft 61 will continuously rotate the clutch members 66 and 67 in opposite directions. A middle clutch member 68 is fixed upon the reversible shaft 60 and is shown as keyed thereto, and a clutch collar 69 is slidable longitudinally upon but (by means not shown) is rotative-

ly coupled to the middle clutch member 68. Expansible split clutch bands 70 and 71 are carried by reduced end portions of the middle clutch member 68 to rotate therewith, the clutch bands 70 and 71 being located, respectively, within the cups formed by the respective cup-shaped outer clutch members 66 and 67, and being adapted to be expanded into frictional clutching engagement therewith so as to be driven thereby. When the slidable clutch element or collar 69 is at its middle position, shown in Fig. 8, the expansible clutch bands 70 and 71 are both free of or out of clutching engagement with the corresponding outer clutch members 66 and 67, so that both of the latter may freely rotate idly, this being the neutral position of the clutch collar 69. Operating connections (not shown) are provided between the slidable clutch collar 69 and each of the expansible clutch bands 70 and 71, and these connections, in the construction shown, are adapted when the clutch collar 69 is slid to the left, as seen in Fig. 8, to expand the left-hand clutch band 70 into clutching or gripping relation with the rotating adjacent outer clutch member 66, the other clutch band 71 remaining out of clutching engagement with the other outer clutch member 67; and when the clutch collar 69 is slid to the right, to expand the right-hand clutch band 71 into clutching engagement with the corresponding rotating outer clutch member 67, while the left-hand clutch band 70 remains disengaged from the left-hand outer clutch member 66. Such operating connections commonly employed in this type of clutch comprise, for each clutch band 70 and 71, a cam wedge carried by the collar 69 and engageable between the adjacent ends of a pair of levers of the second order fulcrumed at their other ends on an end of the middle clutch member 68 and engaging between the ends of the adjacent expansible split clutch band, 70 or 71, as the case may be. In the machine shown in the drawings, the construction and arrangement of the above described power-transmitting parts are such that the above noted left-hand position of the clutch collar 69 is the forward-drive position, for closing the die and clamping it to the nozzle, while the right-hand position of the collar 69 is the backward-drive or reverse-drive position, for opening the die and retracting it from the nozzle, the middle position of the collar 69 shown in Fig. 8 being, as above noted, a neutral or non-driving position.

A clutch shifter for the clutch collar 69 comprises a yoke 72 the arms of which have studs or pins 73 engaging in a circumferential groove in the collar 69, as shown in Figs. 7 and 8, the yoke 72 being fixed upon the lower portion of a rockable shaft 74 journaled in the front part of the frame 32

and having fixed upon its upper end a two-armed clutch-controlling lever 75 overlying the frame 32 and having a shorter forwardly extending arm provided at its end with a yoke-shaped head having short downwardly extending legs 76, and having a longer rearwardly extending bent and offset arm provided with a downwardly spring-pressed pin 77 which at its lower rounded end is yieldingly engageable in any one of three recesses 78, 79 and 80 in the upper side of a lug 81 on the top of the frame 32. It will be evident that when the clutch-controlling lever 75 is in position for the pin 77 to occupy the first or left-hand recess 78 then the clutch collar 69 will be at the forward-drive position; when the pin 77 is in the middle recess 79 as shown in Fig. 3 then the clutch collar 69 will occupy its middle or non-driving position shown in Fig. 8, and when the pin 77 is in the third or right-hand recess 80 as shown in Fig. 4 then the clutch collar 69 will be at the reverse-drive position. For starting the machine in operation, a downwardly extending starting lever 82 is pivoted upon the front of the frame or head 32 and has an upstanding arm engaging at its end between bearing screws 83 in the legs 76 of the clutch-controlling lever 75.

Without necessity of again tracing out the complete operating connections, which have been hereinbefore described, by referring to Fig. 1, in which the operating parts of the machine are at rest with the die open and retracted from the nozzle, although it is assumed that the main drive shaft 61 is rotating, with the clutch in neutral condition, it will be evident that by moving the starting lever 82 toward the left the clutch-controlling lever 75 will be swung from its middle to its first position thereby to shift the clutch collar 69 from neutral to forward-drive or starting position, whereupon the die-carrier-operating rock shaft 57 will begin to rotate in a forward or clockwise direction as viewed in Fig. 1. This rotative movement of the rock shaft 57 will continue until the toggle links 55 thereon have reached a forwardly extending position with the toggle nearly locked at which time and during the final part of the forward traveling movement of the cross-head 42, a traveling tappet screw 84 moving towards the right (Figs. 1, 3 and 4) comes into contact with the offset rear end of the clutch-controlling lever 75 and moves the latter from the forward-drive to the neutral position thereof as shown in Fig. 3, thereby automatically stopping the rotation of the die operating rock shaft 57 at substantially a half turn with the toggle locked and the die closed at the casting position shown in Figs. 3, 13, 15, 16 and 18; the tappet screw 84 being adjustably carried by a tappet

block 85 adjustable along a clutch-controlling rod 86 extending back from the cross-head 42 and adjustably secured thereto by means of nuts 87 and near its free end being guided at 88 in a part of the frame 32, and being further similarly guided at its free end. The machine is now in the condition hereinbefore referred to in which there is provided a die-charging period of rest of 10 the die sections 22 and 23 at the casting position, and as is shown in Fig. 3. It is to be noted in this connection that the tappet screw 84 acts as a positive stop to prevent any possibility of the clutch-controlling lever 75 being shifted from its neutral position back to its forward-drive position, while the die is at the casting position.

When the clutch collar 69 is at its middle or neutral position, either in the idle condition of the operating parts of the machine shown in Fig. 1 or in the casting position of the parts thereof shown in Fig. 3, the reversible operating shaft 60 is free from or has no connection with either of its operating gears 64 or 65 and therefore cannot be controlled or held in position thereby, and in this connection it is to be noted that the worm gearing comprising the worm wheel 58 and the worm 59 plays an important part. 20 In the non-operating condition of the machine shown in Fig. 1 this worm gearing will prevent the die carriers 39 and 44 from sliding down towards the nozzle and will securely hold them retracted from the nozzle. 30 Separately, and separated from each other, by reason of the fact that the worm 59 serves to lock the worm wheel 58 against rotation, as the low pitch of the worm 59 prevents it being driven or rotated by the worm wheel 58. Similarly, in the casting position of the parts of the machine shown in Fig. 3 this worm gearing serves to hold both sets of toggles, hereinbefore described, in securely locked condition, with the die closed and clamped to the 40 nozzle in casting position, and prevents any possibility of the accidental breaking of the toggles, through back lash or otherwise.

As a part of the automatically acting mechanism, an automatic device, driven from the main shaft 61 and controlled by the die-carrier-operating member or cross-head 42, is provided for operating the valve device 14, to cause the molten metal to be shot into the die during its die-charging period of rest, and also for timing and terminating the die-charging period of rest of the die, such device operating to shift the clutch-controlling lever 75 of the hereinbefore described clutch shifter from its neutral to its reverse-drive position, whereby, after the molten metal has been shot into the die and the casting has sufficiently hardened, the die will be opened and retracted from the nozzle, as hereinbefore described. Such device 50 includes a one-revolution clutch, which may

be of any suitable construction, and the particular clutch of this kind shown in the drawings is of a well known construction, is commonly used in various relations, and is commonly known as the "Adrian" clutch. 70 In carrying out my invention, this clutch is shown as built into the machine. It has a shaft 89 journaled in the outer and back part of the frame or head 32 and geared to the main drive shaft 61 to be continuously rotated thereby. For thus rotating the clutch shaft 89, a spur gear 90 fixed on the drive shaft 61 at the back of the machine meshes with a larger spur gear 91 fixed on the outer end of a short intermediate shaft 92 journaled in the frame 32 and which carries a worm 93 engaging a worm gear 94 fixed upon the lower end portion of the clutch shaft 89; the arrangement being such that the clutch shaft 89 will be rotated in a clockwise direction as viewed in Figs. 3 and 4. A clutch member 95, fixed on the clutch shaft 89 to rotate therewith, is provided with a plurality, shown as three, equidistantly circumferentially spaced upwardly projecting 90 driving studs 96. A second clutch member 97, loosely mounted on the clutch shaft 89 above the rotating clutch member 95 and clearing the upper ends of the driving studs 96, has extending therethrough and guided 95 thereby parallel to the clutch shaft 89, a slideable clutch bolt 98, (Fig. 10) which at its upper end extends above the main or larger part of the clutch member 97 into a guide groove in an upper reduced portion or boss 100 100 formed on this clutch member, and the bolt 98 is provided at its upper end with an outwardly projecting lug 100 which is rounded on its lower side. Normally, or when the loosely mounted clutch member 97 105 is not to be driven by the rotating clutch member 95, the clutch bolt 98 is held at its upper and disengaged position by a sharp-ended bolt-disengaging wedge 101 which is engaged under the bolt lug 100, as shown in 110 Fig. 10, this wedge being pivoted on the frame 32 at 102 to be swung laterally out of engagement or into engagement with the bolt 98, a retractile spring 103 being provided to return the wedge 101 into position 115 for engaging the bolt 98 and for yieldingly holding it there. When the wedge 101 is disengaged from the bolt lug 100, the clutch bolt 98 will drop down and its lower end will be engaged by one of the driving studs 120 96 so that thereby the upper loosely mounted clutch member 97 will be coupled to and driven by the rotating clutch member 95. In the operation of the device, through the automatic operation of means presently to be described, the wedge 101 is swung outward out of engagement with the bolt lug 100, and then, before the completion of one rotation of the coupled clutch members, the wedge is released and is returned to its orig- 130

- inal position by its spring 103, whereupon, when the bolt lug 100 comes around it will override the wedge 101, whereby the bolt 98 will be withdrawn from engagement with the driving studs 96 and, at the end of a single rotation, the uncoupled loose clutch member 97 will stop, by reason of frictional resistance, no special abutment-providing stopping means being required.
- 10 During the final part of the forward die-closing and die-clamping movement of the die-carrier-operating member or cross-head 42 and substantially concurrently with the moving of the clutch-controlling lever 75 from its forward drive to its neutral position by the tappet screw 84 as hereinbefore described, the one-revolution clutch is set in operation by a forwardly extending upwardly yieldable finger or pawl 104, pivoted on the controlling rod 86 at 105, striking the upper end of an upstanding stud 106 on the pivoted wedge 101 and moving the wedge out of engagement with the lug 100 of the clutch bolt 98. The pawl 104 as a whole is L-shaped, having an upstanding arm 107 yieldingly held against an abutment pin 108 on the rod 86 by a retractile spring 109 connected thereto and anchored to the rod (Fig. 1). A pair of cams 110 and 111, shown as formed in one piece (Fig. 9), are loosely mounted upon the upper end of the clutch shaft 89 and, by means of interengaging teeth (Figs. 9 and 10), are connected to the loosely mounted clutch member 97 to be rotated thereby, these interengaging teeth being formed, respectively, on the lower end of a reduced downward extension 112 from the lower cam 111, and on the upper end of a similar reduced upward extension 113 from the boss 99 of the clutch member 97, the clutch member extension 113 being journaled in the frame 32, so that the loose clutch member 97 forms a bearing for the clutch shaft 89. As the cams rotate with the coupled clutch member 97 a radially projecting pin 114 on the periphery of the upper cam 110 strikes the upstanding arm 107 of the pawl finger 104 and raises the latter out of engagement with the wedge stud 106, permitting the wedge 101 to be moved by its spring 103 into position for withdrawing the clutch bolt 98, thereby bringing the cams 110 and 111 to a stop at the end of a single rotation.
- 15 The clutch-driven upper cam 110 forms a part of a cam device for automatically operating the valve device 14 to admit pressure fluid to the pressure chamber or melting pot 4 and exhaust it therefrom while the die is held at rest in the casting position, by reason of the clutch-controlling lever 75 remaining at its neutral position, thereby to eject the molten metal from the pressure chamber 4 through the nozzle 7 into the die.
- 20 The cam 110 is shown as a double acting or double faced cam having in its upper side a continuous cam groove 115 having a long inner circumferential portion and a short outer circumferential portion joined by inclined portions to provide a sloping cam projection 116 and an inclined cam shoulder 117. The cam groove 115 receives a cam roller 118 on the adjacent end of a slidable bar 119 guided at 120 in the frame 32 and pivoted at its other end to the inner and shorter arm of a straight lever 121 of the first order pivoted at 122 on the top and back part of the frame 32 and having a longer rearwardly projecting arm to which there is connected one end of a pull chain 123 which extends to the right and downward and has its other end connected to the valve-operating lever 19 of the valve device 14. When the cam roller 118 is in the long inner circumferential portion of the cam groove 115 (Figs. 3 and 4) there will be no pull upon the chain 123, but the cam 110 is so timed that immediately after the die sections 22 and 23 have been locked together and the inner die section 22 locked to the nozzle 7, the cam projection 116 will engage the cam roller 118 and will push the bar or link 119 to the right, as viewed in Fig. 3, thereby causing the lever 121 to exert a pull upon the chain 123 which will lift the outer end of the valve lever 19, so that the latter depresses the valve stem 17, whereby, in the manner hereinbefore described, pressure fluid is admitted into the pressure chamber 4 to force the molten metal therefrom into the die. After a short interval, during which the die is filled, with the cam roller 118 in the short outer circumferential portion of the cam groove 115, the continued rotation of the cam 110 causes the cam shoulder 117 to engage the cam roller 118 and retract the bar 119, thereby causing the lever 121 to release its pull upon the valve-operating chain 123 and permitting the valve-closing spring 18 to lift the valve stem 17, thereby, in the manner hereinbefore described, shutting off the supply of pressure fluid to the pressure chamber 4 and exhausting the pressure fluid therefrom; the pressure fluid being exhausted from the pressure chamber while the die is still in the closed condition and clamped to the nozzle in casting position; and the die is now left at the casting position for a further proper period of time for the casting to cool and harden to a safe extent, as will presently appear.
- 25 A second cam device, including the lower clutch-driven cam 111, is provided for automatically shifting the clutch-controlling lever 75 of the clutch shifter from its neutral position shown in Fig. 3 to its reverse-drive position shown in Fig. 4, whereby, through the operation of the reversed reversing gearing, the die will be opened and

retracted from the nozzle, as hereinbefore described. The cam 111 has a peripheral cam face made up of a long inner or depressed circumferential part and a shorter but comparatively long circumferentially faced cam rise or projection 124 which slopes gradually at its leading end and terminates abruptly (Fig. 4). The cam face of the cam 111 engages a cam roller 125 on the adjacent end of a diagonally arranged slidable push bar 126 which at its other end is engageable with the inclined or bent portion of the clutch-controlling lever 75, the push bar 126 being provided with a guide 127 on the frame 32 and being further guided in the latter adjacent the cam roller 125. The push bar 126 is of a length so that when its cam roller 125 is opposed to the inner or depressed part of the cam face of the cam 111, this push bar will not obstruct the movement of the clutch-controlling lever 75 to the starting or forward-drive position, but when the cam roller 125 rides onto the cam projection 124 the free end of the push bar 126 will engage the clutch-controlling lever 75 and push it from its neutral position shown in Fig. 3 to its reverse-drive position shown in Fig. 4, whereupon the die will be opened and retracted from the nozzle, as hereinbefore described. The cam 111 is so timed that the cam projection 124 will engage the cam roller 125 after the molten metal has been shot into the die and the fluid pressure thereon released, and also after a suitable predetermined period of rest of the die at the casting position, for the hardening of the casting. It is to be noted that the cam projection 124 is of sufficient circumferential length that it will positively hold the clutch-controlling lever 75 at the reverse-drive position substantially throughout the return movement of the die carriers 39 and 44. Immediately after the cam roller 125 escapes the abrupt end of the cam projection 124, a backwardly traveling tappet screw 128 carried by the clutch-controlling rod 86, and adjustable through a tappet block 129 which is adjustable along this rod, will engage the outer offset end of the clutch-controlling lever 75 and will shift the latter from the reverse-drive to the neutral position, thereby, in the manner hereinbefore described, stopping the reverse rotation of the die-carrier-operating rock shaft 57, with the die carriers 39 and 44 at rest in the open and retracted position of the die sections 22 and 23 shown in Fig. 1, the die carriers having now been moved through a complete cycle, and a complete cycle of operations of all parts of the machine has now taken place, although some of these parts and operations are yet to be described. It is to be noted that the tappet screw 128 in engagement with the clutch-controlling lever 75 will now prevent the shifting of this

lever from the neutral to the reverse drive position.

An automatically operated safety device is provided to prevent the admission of pressure fluid to the pressure chamber 4 at any other time except when the die is closed and clamped to the nozzle 7 in casting position. Otherwise such admission might possibly occur accidentally, for example, by reason of a person inadvertently coming into contact with the valve-opening chain 123. This safety device includes the valve device 21, which forms a safety valve. The valve device 21 is of substantially the same construction as the valve device 14, and has a corresponding depressible valve stem 130, and valve-closing spring 131. The main pressure fluid supply pipe 20 is connected to the inlet port of the valve device 21, its delivery port is connected to the pipe 15 leading to the valve device 14, and the exhaust port is connected to an exhaust pipe 133. A long rockable valve-operating lever 134, pivoted at its lower end upon the valve body or casing, is pivotally connected at its upper end to a small downwardly extending rock arm 135 carried by the front end of a small transverse rock shaft 136 journaled in bearings 137 on the lower side of the cross bar 28. The rock shaft 136 has fixed medially thereon a small downwardly projecting operating arm 138. The inner die carrier 39 is provided at its lower edge with a downwardly projecting bracket arm 139 which carries an adjustable tappet screw 140, the operating arm 138 being in the terminal part of the path of movement of this tappet screw, as the die carrier 39 moves toward the nozzle 7. Just before the die section 22 comes into contact with the nozzle 7, the tappet screw 140 engages the operating arm 138 and rocks the valve-operating lever 134, thereby operating the valve device 21 to admit pressure fluid from the main supply pipe 20 to the pipe 15, and hence just prior to the opening of the valve of the valve device 14, hereinbefore described. When the die section 22 is retracted from the nozzle 7, the tappet screw 140 will be retracted and the valve-operating lever 134 will be rocked in the opposite direction, thereby permitting the valve spring 131 to close the valve of the valve device 21, communication at the same time being opened between the secondary supply pipe 15 and the exhaust pipe 133; hence when the valve 21 is thus closed, the valve 14 has already been closed, in the manner hereinbefore described. It will now be evident that the valve 21 is open only substantially during the time that the valve 14 is open, and is closed at all other times.

Automatically operated core-pulling and casting-ejecting mechanisms are provided as features of my invention, and will now be

- described, such mechanisms being carried by the second or outer die carrier 44 and being arranged to be operated by the relative movement of the die carriers, through operating means connected to the first or inner die carrier 39 to move therewith. In the machine shown in the drawings as an embodiment of my invention, the core-pulling and the casting-ejecting mechanisms are to some extent combined in that they share or have some parts in common, as will presently appear; also in some respects these two mechanisms or devices bear a close resemblance, having similar features of construction; therefore the description of these mechanisms must to some extent be in common, although their different operations are performed at different times in timed relation, the cores being first withdrawn and then the casting ejected.
- 20 The core-pulling mechanism will be first considered.
- The operating means for the greater part of the core-pulling mechanism comprises a rack bar 141 which at one of its ends is adjustably connected by means of nuts 142, to the lower and front part of the cross-head 42, which latter, as hereinbefore described, is connected to the first or inner die carrier 39 by the rods 43. The other end portion of the rack bar 141 is guided in the outer die carrier 44, and the rack teeth thereon engage a spur gear 143 on its forward side, the relation in the construction shown, being such that this gear will be rotated through about 35 a one-half turn, in a counter-clockwise direction, as viewed from above (Fig. 17), as the die sections are separated, and similarly in the opposite direction as the die sections are brought together. The gear 143 is connected to or carries an inner cam 144, and an outer second cam 145 is formed in one piece with the inner cam 144. The gear 143 and the cams 144 and 145 carried thereby are loosely journaled on a stub shaft 146 40 screwed at its upper end into the lower side of the die carrier 44 (Fig. 13).
- The inner or upper cam 144 has in its upper side a cam groove 147 in which engages a cam roller 148 on the lower side of the adjacent end of a short rack member 149 slidably guided in the lower part of the die carrier. On its forward toothed side the rack member 149 engages the lower end of a toothed pinion-forming shaft 150 (Figs. 12 45 and 17) journaled in and extending upward through the die carrier, as shown in dotted lines at the left in Fig. 12, this pinion shaft being held in place by a screw pin 151 entering a circumferential groove in the upper end thereof. The pinion shaft or long pinion 150 engages rack teeth formed on the forward sides of a pair of similar plungers 152 guided in the die carrier to slide parallel with the carrier-guiding rods 43, each 50 plunger including a forward extension 153

secured thereto by a longitudinal bolt 154 (Fig. 13). The forward ends of the plunger extensions 153 carry a core-operating plate 155; and the plate 155 has detachably affixed thereto a core-carrying plate 156 shown as provided with two large cores 157 and 158 and a small core 158^a which extend through the backing plate 46 and die section 23, and which are adapted to be projected into the die cavity 24, as shown in Figs. 13, 15, 16 and 18, or to be withdrawn as in Figs. 1 and 17.

The outer or lower cam 145 has in its periphery, and extending a little more than half way around, a cam groove 159 in which engages a cam roller 160 on the forward side of a comparatively short rockable lever arm 161 carried, at the back of and below the die carrier, upon the adjacent end of a squared transverse horizontal fulcrum-forming rock shaft 162 having round ends pivoted on the lower ends of downwardly extending lugs 163, on the die carrier 44, and held in place by detachable bearing caps 164 (Figs. 1, 12 and 13). A longer core-pulling lever 165 is 50 fixed at one end on the rock shaft 162 to be adjustable therealong and is shown (Fig. 12) as just forward of the middle of this shaft. The core-pulling lever 165 projects forwardly beneath the die section 23 and at 55 this end rigidly carries an upwardly extending rod 166 (Fig. 1) which is adjustable along the lever, to vary the effective length of the latter, by means of nuts 167 and a toothed upper washer 168 engaging serrations on the upper side of the lever, the lower end of this rod passing through a slot in the end of the lever. By means of a short link 169, (Figs. 1, 14 and 16) the upper end of the rod 166 is pivotally connected to a 60 core head 170 to which is connected the lower end of a large core 171 which is guided in a lug on the face of the outer die section 23 and which is adapted to have its upper end projected upwardly into the die cavity 110 24, as shown in Figs. 14 and 16, or to be withdrawn downwardly therefrom, as in Fig. 1.

A second rack bar 172, similar to the rack bar 141, operates more of the core-pulling mechanism and also operates the casting-ejecting mechanism, presently to be described. At its rear end the second rack bar 172 is adjustably connected, by means of nuts 173, to the back and upper part of the cross-head 42. The forward end of the rack bar 172 is guided in the outer die carrier 44, and its rack teeth engage a spur gear 174 at the back thereof, this gear forming a part of both the core-pulling and ejector mechanisms. The gear 174 is similar to the gear 143 and similarly has substantially one-half rotations, alternately in opposite directions, imparted thereto, so that when the die sections are separated the gear 174 will rotate 115 120 125 130 135

in a clockwise direction as viewed from above in Fig. 1 and as seen in plan in Fig. 3, and will be rotated in the opposite direction as the die sections are brought together, 5 as shown in Figs. 3 and 13. The gear 174 is connected to or carries an inner or lower cam 175, and an outer or upper second cam 176 is formed in one piece with the lower cam 175, the lower cam 175 forming a part 10 of the casting-ejecting mechanism, while the upper cam 176 forms a part of the core-pulling mechanism. The gear 174 and the cams 175 and 176 carried thereby are loosely journaled on a stub shaft 177 screwed at its lower 15 end into the die carrier 44 (Fig. 13).

The upper or core mechanism cam 176 has in its periphery, and extending a little more than half way around, a cam groove 178 in which, at the front of the cam, engages a 20 cam roller 179 on the adjacent end of a lever arm 180 carried at its other end upon an upper transverse horizontal fulcrum-forming square rock shaft 181 journaled at its round ends on the upper ends of lugs 182 25 projecting up from the die carrier 44, and held in place by detachable bearing caps 183 (Figs. 1, 3, 12 and 13). A core-pulling lever 184, longer than the arm 180, has one end fixed on and adjustable along the square 30 shaft 181, being shown (Figs. 3 and 12) as at the middle of this shaft. The core-pulling lever 184 projects at its forward end above the die section 23 and there rigidly carries a downwardly extending rod 185 35 (Figs. 1 and 13) which, by means of nuts 186 and a toothed lower washer 187 engaging serrations on the lower side of the lever, is adjustable along the lever, thereby to vary the effective length of the latter, the upper 40 end of this rod passing through a slot in the end of the lever. A short link 188 (Figs. 13 and 14) pivotally connects the lower end of the rod 185 to a core head 189 to which is connected the upper end of a small core 45 190 which is guided in the die section 23 and is adapted to have its reduced lower end portion projected downwardly into the die cavity 24, as shown in Figs. 13, 14 and 18, or to be withdrawn upwardly therefrom, as 50 in Fig. 1.

It is to be noted that the cores 157, 158 and 158^a, carried by the core plate 156, have withdrawing and repositioning movement in the same direction or in line with the movement of the die carriers 39 and 44, while the movement of the oppositely moving cores 171 and 190, as they are withdrawn or repositioned, is transverse to the direction or line of movement of the die carriers. It is 55 of course to be understood that the several above noted cores are to be used only with the particular die shown, for producing the particular casting shown in Figs. 19 and 20, and that other cores differently located may

be employed when the die is changed for 65 casting other objects.

The particular cast object shown in Figs. 19 and 20 comprises two independent castings 191 and 192 joined together by a tubular sprue 193 having thin fins 194 and 194^a, 70 from which the two castings 191 and 192 may be easily broken off, as an after operation. It is desirable of course to have as little metal as possible in the sprue while at the same time providing for freedom of flow, 75 and therefore the large taper-ended central core 157 is employed to extend into the die gate 25 and at its extreme tapered end into the port 41 of the nozzle 7, as shown in Figs. 13 and 18. The large central bore in the upper casting 191 is produced by the large upper core 158 on the core plate 156, and the small counterbore by the small upper transverse core 190; while the large bore in the head end of the lower casting 192 is produced by the lower large transverse core 171, 80 and the small counterbore by the small lower core 158^a carried by the core plate 156; as is clear from the drawings.

The contour of their cam grooves and the 90 timing of the above described core-pulling cams 144, 145 and 176 are such that all the above described cores will be withdrawn from the casting during the separating movement of the die sections, and sufficiently 95 before the completion of this movement to allow for the ejector mechanism to operate to eject the casting during the final or terminal part of this movement and after the cores have been withdrawn.

For use with other dies, when the die is changed for making different kinds of castings, core-pulling levers 195 and 196, shown in broken lines in Figs. 12 and 17, may be installed upon the front and back of the die carrier 44, on the supporting lugs 197 and 198 there provided, together with suitable lever-operating cam devices 199 and 200, indicated in outline by broken lines, and provided for by the transverse bores 201 and 202, in the die carrier, this mechanism being 105 similar to that above described for operating the lower and upper core-pulling levers 165 and 184, and being similarly operated, and the core-pulling levers 195 and 196 being adapted to pull cores from the front and back, respectively, as shown in Fig. 17. Also it is to be understood that the lower and upper core-pulling levers, together with their operating devices may be detached and removed, and, if desired, may be installed at the front and back of the die carrier 44, the same as the outlined core-pulling levers 195 and 196 and their operating devices 199 and 200.

The casting-ejecting mechanism will now be described. This mechanism, as hereinbefore stated, includes the upper spur gear

174 and the adjacent ejector cam 175, and this ejector mechanism is similar to that part of the above described core-pulling mechanism for operating the core-operating plate 155, for the cores which pass through the die section 23. The ejector cam 175 has in its lower side a cam groove 203 (Figs. 3, 12 and 13) in which engages a cam roller 204 on the upper side of the adjacent end of a short rack member 205 slidably guided in the upper part of the die carrier 44. On its rear toothed side the rack member 205 engages the upper end of a long pinion or pinion shaft 206 (Figs. 3, 12 and 17) journaled in and extending downward through the die carrier at the rear of the core mechanism pinion shaft 150, as shown in dotted lines at the right in Figure 12, this pinion shaft 206 being held in place by a screw pin 207 entering a circumferential groove in the lower end thereof. The pinion shaft 206 engages rack teeth formed on the rear sides of a pair of similar ejector plungers 208 guided in the die carrier to slide parallel with the carrier-guiding rods 43. An ejector plate 209 is secured upon the forward ends of the ejector plungers 208 by means of long bolts 210 passing through the tubular plungers. The ejector plate has detachably affixed thereto a pin-carrying plate 211, and it is to be noted that the plunger extensions 153 of the core mechanism plungers 152 pass through the ejector plate 209 and the pin-carrying plate 211. The pin-carrying plate 211 is shown as provided with a plurality, shown as seven, of small ejector pins 212, and with two larger pins 213, all of which extend through the core-operating plate 155 and core-carrying plate 156, and also extend through the backing plate 46 and die section 23. The smaller ejector pins 212 may be projected beyond the face of the die section 23, as shown in Figs. 1 and 17, for ejecting the casting shown in Figs. 19 and 20, or may be retracted into the die section, as shown in Figs. 13, 15, 16 and 18. The larger and stronger pins 213 in the present case do not perform an ejecting function, but serve as rigid guides for the smaller ejecting pins 212, and also for the cores carried by the plate 156.

It is to be understood that other ejector pins, differently located, may be employed for ejecting castings other than that shown in Figs. 19 and 20, upon the die being changed.

The timing of the ejector cam 175 and the contour of its cam groove 203 are such that the ejector pins, such as 212, will be projected to eject the casting during the final part of the separating or die-opening movement of the die sections 22 and 23, and after the cores have been withdrawn, as hereinbefore described.

The die may be cooled in any suitable way, such as by circulating a suitable cooling medium through the die sections, water being commonly employed; and for this purpose, the die sections 22 and 23 are shown as having through them channels or openings 214 (Figs. 1, 11, 13, 14, 16, 17 and 18) to which pipes 215, (Figs. 11, 14 and 17) are shown as connected. The die section 23 is provided with usual dowel pins 215^a, to enter corresponding holes 215^b in the other die section 22, to assure the accurate alignment of the die sections at the casting position.

The automatically operated metal replenishing feed mechanism provided for automatically feeding ingots to the casting pot or pressure chamber 4, which also is a melting pot, will now be described. This mechanism, as has been hereinbefore noted, is, in a general way, similar to that forming the subject of the hereinbefore mentioned patent to Pack. However, not only does this mechanism in a general way form a feature in combination in the complete machine of my present invention, but also such mechanism contains features involving my invention and which more particularly adapt it for entering into such general combination.

Cylindrical ingots 216 are contained in a trough or open top chute 217 and in the upper end of a tubular feed chute 218 which extends downward from the bottom of the trough 217 and opens into the upper end of the combined melting pot and pressure chamber 4 through its cap 5. The trough 217 is slightly inclined from the horizontal so that the ingots will roll down into the upper end of the tubular chute 218, their entry being assured by an abutment 219 in the trough 217, and the tubular chute 218 is shown as slightly inclined from the vertical and as arranged at right angles to the trough 217. The trough 217 extends out towards the machine head 32 and is provided with braces 220 and 221 connected to the furnace 1.

An automatically operated ingot-feeding escapement device is provided to drop the ingots 216 one by one through the feed tube 218. A short lever 222 is pivotally fulcrumed at its middle on a lug 223 projecting from a bracket plate 224 mounted upon the upper end of the feed tube 218 at the right side thereof as viewed in Fig. 1, this lever extending along the feed tube 218 near the upper end thereof. The lower end of the lever 222 is pivoted to the outer end of an ingot-engaging finger 225 passing through and guided in an opening in the feed tube 218, and the upper end of the lever 222 is pivoted to a similar finger 226, this latter finger, however, being extended outward and having pivoted to its outer end the upper

- end of an operating lever 227 of the first order which below and outward from the lower end of the finger-connected lever 222 is pivotally fulcrumed on a lug or bracket 228 projecting from the lower end of the bracket plate 224, the lower and longer arm of the operating lever 227 being bent first outwardly and then downwardly. It is evident that by rocking the operating lever 227 5 in one direction and then in the other, the inner ends of the fingers 225 and 226 will be alternately projected into the path of the ingots 216, and correspondingly withdrawn therefrom, in Fig. 1 the lower finger 225 being shown as thus projected, beneath the lowermost ingot, while the upper finger 226 is withdrawn. Upon outward movement of the lower end of the operating lever 227, the lower finger 225 will be withdrawn to 10 permit the lowermost ingot to drop through the feed tube 218, while the upper finger 226 will be projected into the path of the next following ingot. Upon inward movement of the lower end of the operating lever 227, the upper finger 226 will be withdrawn and the lower finger 225 will be projected into the feed tube 218, so that the lowermost ingot will escape past the upper finger 226 and will now rest upon the lower finger 225, the 15 condition now being again the same as shown in Fig. 1.
- An automatically operated valve is provided in the feed tube 218 below the above described ingot-feeding device, to be kept 20 closed when there is pressure of pressure fluid in the pressure chamber 4, to prevent the escape of the pressure fluid, and to be opened at a time when there is no pressure of pressure fluid in the pressure chamber 4, 25 to provide for the dropping of an ingot 216 through the feed tube 218 into the pressure chamber 4 to replenish the metal therein. Such valve is shown as a gate valve comprising a valve casing 229 connected in the 30 feed tube 218 and providing a seat for a wedge-shaped valve gate 230. The slidable valve gate 230 has connected thereto an operating rod 231 provided with spaced adjustable nuts 232 between which the lower 35 end of the operating lever 227 of the ingot-feeding device engages, so that thereby a connection is formed between the valve gate 230 and the above described ingot-feeding device to coordinate their movements so as 40 to assure or compel their concurrent operation, the arrangement being such, as will be evident from Fig. 1, that when the valve gate 230 is opened the lowermost ingot will be released by the lower finger 225, to drop 45 through the feed tube 218 and unobstructed valve casing 229 of the open valve into the pressure chamber 4, the reserve supply of ingots then being held back by the upper finger 226, and then when the valve gate 230 is closed the ingots 216 will be released by 50 the upper ingot-holding finger 226 and will descend upon the lower ingot-holding finger 225, as shown in Fig. 1.
- Automatically controlled fluid pressure operated means are provided for effecting 55 the above described concurrent operation of the chute-controlling gate valve and the ingot-feeding device. The operating rod 231, which is a piston rod, carries at its outer end from the valve gate 230 and is operated 60 by a double-acting piston 232 in a cylinder 233 supported at the rear of and upon the top of the fire box 1 by a bracket 234. A suitable pressure fluid, such as compressed air, for operating the piston 232, is admitted 65 to the cylinder 233 through pipes 235 and 236 connected to the opposite ends of this cylinder, and the used pressure fluid is exhausted from the cylinder through the same pipes. When piston-operating pressure fluid is admitted to the cylinder 233 through the pipe 235, at the left end thereof as viewed in Fig. 1, the valve gate 230 will be opened and an ingot dropped into the pressure chamber 4, and when the pressure fluid is admitted to the cylinder 233 through the pipe 236, at the other end thereof, the valve gate 230 will be closed and an ingot 70 permitted to descend onto the lower finger 225.
- Automatically operated fluid pressure controlling means are provided in control of the pressure fluid to cause the proper operation of the piston 232 in the cylinder 233. Such means may include any suitable valve mechanism in control of the pressure fluid, and the valve device 237 shown in Fig. 1 is a common form of four-way valve, of the rotary type, and therefore need not have all its details of construction shown. The pipes 75 235 and 236, connected to the opposite ends of the cylinder 233, are connected at their other ends to the valve device 237; also connected to the valve device 237 are a pressure fluid supply pipe or inlet pipe 238 and an 80 exhaust pipe 239, the supply pipe 238 at its other or intake end being connected to the main supply pipe 20. The valve device 237 is shown as located in an inclined position 85 at the rear of the fire box 1 and as supported 90 by means of a bracket 240 mounted on the adjacent side rod 29. The valve device 237 has a rockable stem or spindle 241 which projects to the outside at its lower end, and the arrangement is such that when this valve 95 stem is rocked in one direction, for example, in a clockwise direction as viewed from below, pressure fluid will be admitted to the left end of the cylinder 233 through the pipe 235 and will be exhausted from the other 100 end of the cylinder through the pipe 236, thereby to open the valve gate 230 and to cause the ingot on the lower finger 225 to be dropped thereby, and when the valve stem 105 241 is rocked in the opposite direction, the 110

valve gate 230 will be closed against escape of pressure fluid from the pressure chamber 4, an ingot will be let down upon the lower finger 225 in readiness to be dropped thereby, as shown in Fig. 1.

In carrying out my invention, operating means are provided and operated automatically from a suitably moving part of the machine, for automatically operating the 10 fluid pressure controlling valve device 237 in proper timed relation with the operation of the hereinbefore described automatically operated valve device 14, so as thereby to assure the feeding of ingots to the pressure 15 chamber 4 only at such times as there is no pressure of pressure fluid therein; such operating means embodying automatically acting selective controlling means, comprising a selector device, whereby the frequency of the 20 ingot-feeding operations relatively to the casting operations may be varied as desired. Such selective controlling means play an important part by reason of the fact that commonly each ingot 216 contains enough metal 25 for several casting operations, the number of such operations per ingot depending upon the size of the castings, which may vary considerably upon changing the die for the casting of different articles. By reason of the 30 selectively operating controlling means employed, an ingot 216 may be fed to the pressure chamber 4 for each casting operation or only at intervals following a predetermined number of casting operations, as may be desired. The above noted operating means, together with the controlling means therefor, will now be more particularly described.

A stationary stud or stub shaft 242 projecting backwardly at the back of the fire 40 box 1 has loosely mounted thereon a ratchet wheel 243 which has ratchet teeth, shown as twelve in number, which are rather long radially, and thereby provide correspondingly deep notches between the ratchet teeth. At 45 the successive casting operations, the ratchet wheel 243 is rotated step by step in the forward or a clockwise direction, as viewed in Figs. 1, 5 and 6, one step or to the extent of one tooth at each casting operation, by means 50 of a two-armed rocker 244 loosely pivoted or fulcrumed on the stud 242 at the rear of or outwardly from the ratchet wheel 243. The rocker 244 has a lower rock arm extending beyond the periphery of the ratchet wheel 55 243 and there provided with a pivoted spring-pressed pawl 245 engageable with the successive teeth of the ratchet wheel to rotate it as above described. The rocker 244 has an upper rock arm to which is pivoted 60 one end of a link rod 246 the other end of which is pivoted to a short upwardly extending rock arm 247 fixed upon the rear end of the transverse rock shaft 136. This rock 65 shaft and the means for rocking it have been hereinbefore described in connection with

the hereinbefore described safety valve device 21, so that it now becomes apparent that this rock shaft and its operating means serve a double purpose.

When the tappet screw 140 carried by the 70 inner die carrier 39, comes into contact with the operating arm 138, on the rock shaft 136, in the final part of the forward travel of this die carrier and before the die section 22 comes into contact with the nozzle 7, the 75 rocking of the rock shaft 136, in a counter-clockwise direction, as viewed in Fig. 1, will cause the ratchet pawl 245 to move back idly over one tooth of the ratchet wheel 243, while the latter remains stationary. When 80 the tappet screw 140 is retracted by the backward movement of the die carrier 39 as it moves the die section 22 away from the nozzle 7, the pawl 245 engages a tooth of the ratchet wheel 243 and rotates the latter one 85 step or one tooth, this movement for rotating the ratchet wheel 243 being imparted to the rocker 244 by a retractile spring 248 connected to its upper rock arm, a stud or pin 249 providing a stop for the rocker 244 when it 90 is thus moved by the spring 248. A rockable finger 250 is loosely mounted to rock on the stud 242 at the other side of the ratchet wheel 243 from the rocker 244, the tip of this finger terminating outward from the bottoms of the ratchet wheel notches and inward from the ends of the ratchet wheel teeth, and shown as terminating at about one-third of the length of the teeth. The 95 lower end of the finger 250 has thereto a substantially radial slot 251 in which works a pin 252 on the adjacent end of a slideable rack bar 253 provided with a guide 254 extending from the lower end of the valve device 237. The other end portion of the rack bar 253 has thereon rack teeth engaging a pinion 255 which is fixed upon the lower end of the rockable valve stem 241 of the valve device 237, the rack bar 253 passing to the 100 rear of the pinion 255 as viewed in Fig. 1, as 105 is indicated by the rack teeth appearing on the rack bar 253 in Figs. 5 and 6. The rack bar 253 is normally held at its right hand position, as viewed in Figs. 1, 5 and 6, by a retractile spring 256 shown as connected to the rockable finger 250, to hold it against a 110 stop pin 257, this position of the finger 250 and rack bar 253 corresponding to the closed condition of the chute-controlling valve gate 230 shown in Fig. 1. When the finger 250 is in this position, it overlies one of the teeth of the ratchet wheel 243, but terminates short thereof, and also is not quite flush with the radial or abrupt side of the tooth. Means 115 for causing the pawl 245 to engage and operate the finger 250, or to prevent such engagement and operation, as may be desired, will 120 now be described.

The ratchet wheel 243 carries a complete 125 circular series of twelve radially arranged 130

pawl-controlling settable selector blocks 258 arranged in radial alignment with the ratchet wheel notches, and forming lugs upon the side of the ratchet wheel 243 adjacent the 5 rockable finger 250. Each selector block or lug 258 is firmly secured on the ratchet wheel 243 by a pair of bolts 259 passing through a longitudinal slot in the block and providing for radially setting the block to an inner or 10 to an outer position on the ratchet wheel. By setting the selector blocks 258 inward, the ratchet wheel notches will be completely uncovered for the full length of the teeth, and by setting these blocks outward, the 15 ratchet wheel notches will be covered to about one-half the radial length of the ratchet wheel teeth, so that the outer ends of the outwardly set blocks 258 will extend radially beyond the outer end or tip of the 20 rockable valve operating finger 250, as is clearly shown in Fig. 6. In the drawings, two diametrically opposite selector blocks 258 are shown as set at their inner or notch-clearing position, while the remainder of 25 these blocks are at their outer or notch-covering position. Obviously, instead of setting the selector blocks 258 to their inner position, they may be removed, if desired, but such removal is unnecessary. The pawl 30 245 is of a width to extend past the selector blocks or lugs 258, so as to be engageable with the finger 250. It is to be observed that any selector blocks or lugs 258 at their inner position on the ratchet wheel 243 will permit the pawl 245 to seat fully in the corresponding ratchet wheel notches, while any such blocks at their outer position will, at 35 their outer ends, hold the pawl 245 partly out and prevent its seating fully in the corresponding ratchet wheel notches.

When the tappet screw 140 comes into contact with the lever arm 138, the rocker 244 will be rocked in a counter-clockwise direction, as viewed in Figs. 1, 5 and 6, and the 40 pawl 245 will ride idly over one tooth of the ratchet wheel 243, as hereinbefore described. Also obviously the rockable valve operating finger 250 cannot be operated by the pawl in this retractive movement thereof, and accordingly the valve gate 230 will remain 45 closed, as shown in Fig. 1, during the time that there is pressure of pressure fluid in the pressure chamber 4 for ejecting the molten metal therefrom into the die. When the tappet screw 140 is retracted from the lever arm 138, after the pressure fluid has been exhausted from the pressure chamber 4, the spring 248 will rock the rocker 244 in a clockwise direction, and the pawl 245 will rotate 50 the ratchet wheel 243 forward one tooth, as hereinbefore described. At this time should the pawl be fully seated in one of the ratchet wheel notches, as shown in Fig. 6, by reason of the corresponding selector block 258, being at its inner position, the pawl 245 will

engage the tip of the rockable finger 250, and will rock this finger in a clockwise direction, thereby, through the above described instrumentalities, causing the valve gate 230 of the gate valve to be opened and an ingot 55 216 to be dropped into the pressure chamber 4. It is to be understood in this connection that the rocker spring 248 is strong enough to overcome the spring 256 employed for retracting the rockable finger 250 and slideable 60 rack bar 253. The valve gate 230 will now remain open until at the next casting operation when the tappet screw 140 engages the lever arm 138, causing the pawl 245, in its retractive movement, to ride outward on a 65 ratchet tooth and release the rockable finger 250, whereupon the latter will be returned to its original position by its spring 256, thereby closing the valve gate 230 in the feed tube 218 prior to the admission of pressure fluid 70 into the pressure chamber or casting pot 4. Should the pawl 245 be held partly out of a ratchet wheel notch by one of the selector blocks or lugs 258 at its outer position this pawl, while imparting a step of rotative 75 movement to the ratchet wheel 243, will pass by the outer end or tip of the rockable finger 250, so as not to operate it, and the valve gate 230 accordingly will remain closed, and no ingot will be fed to the pressure chamber 80 or melting pot 4. It will now be evident that the automatic ingot-feeding mechanism shown in the drawings provides for varying the frequency of the feeding operations all 85 the way from the feeding of an ingot at each casting operation to the feeding of an ingot only at each twelfth casting operation, thereby providing, by changing the die, for the making of castings of widely varying sizes. The ingot-feeding mechanism in the machine 90 shown in the drawings is shown as arranged to feed an ingot 216 to the melting pot or pressure chamber 4 at each sixth successive casting operation.

The operation of the machine as a whole 95 and of its several mechanisms has been hereinbefore so fully explained that only a very brief and general explanation need now be added. Beginning with the position of rest of the operating parts of the machine illustrated in Fig. 1, upon the hand lever or starting lever 82 being moved to the left, to initiate a casting operation, the machine itself will automatically perform all the operations involved in the complete casting operation, throughout a complete cycle, and all 100 the operating parts of the machine will return to and automatically stop at their original position, in readiness for the next casting operation. The die sections 22 and 23 will be closed and locked together and at the same time the inner die section 22 will be moved into contact with and locked to the nozzle 7. During the closing together of 105 the die sections the cores are repositioned in 110

the die section 23 and the ejector pins thereof withdrawn, just as the die section 22 is closing upon the nozzle the safety valve 21 is opened, then after the locking of the die sections at the casting position the supply valve 14 is opened to cause the molten metal to be forced from the combined melting pot and casting pot or pressure chamber 4 into the die, then the pressure fluid is exhausted from the pot 4 by the valve device 14, then, after a suitable period of rest for the casting to harden, the die sections are unclamped and retracted from the nozzle and from each other, just after the inner die section leaves the nozzle the safety valve 21 is closed, and at this time an ingot is dropped into the pot 4, providing the metal is to be replenished at this particular casting operation, as the die section 23 moves back the cores therein are withdrawn, and after this the ejector pins are projected from the die section 23 to eject the casting therefrom, and finally, excepting as to its continuously rotated driving parts, the machine stops.

It is to be understood that the construction shown in the drawings and herein particularly described as one embodiment of my invention may have various modifications made therein without departing from the spirit of the invention or the scope of the appended claims.

I claim:

1. A die casting machine comprising a pressure chamber for the material to be cast provided with a discharge nozzle, a movable die carrier for one part of a sectional die, a movable die carrier for another part of the sectional die, means for moving the die carriers relatively to each other and to the nozzle to close the die and clamp it to the nozzle and to hold the die for a time at the casting position and thereafter to unclamp the die from the nozzle and separate the die sections, mechanism for automatically operating said means through a complete cycle, means for applying pressure to the material in the pressure chamber to force said material into the die, mechanism for automatically operating said pressure-applying means to apply and release the pressure during the time that the die is closed and clamped to the nozzle, and automatically operated core-pulling mechanism for withdrawing cores from the die and repositioning them therein.
2. A die casting machine comprising a pressure chamber for the material to be cast provided with a discharge nozzle, a movable die carrier for one part of a sectional die, a movable die carrier for another part of the sectional die, means for moving the die carriers relatively to each other and to the nozzle to close the die and clamp it to the nozzle and to hold the die for a time at the casting position and thereafter to unclamp the die from the nozzle and separate the die sections, mechanism for automatically operating said means through a complete cycle, means including a valve device for admitting a fluid under pressure into the pressure chamber to eject said material through the nozzle directly into the die and thereafter to exhaust the pressure fluid from the pressure chamber, means for automatically op-

tions, mechanism for automatically operating said means through a complete cycle, means for applying pressure to the material in the pressure chamber to force said material into the die, mechanism for automatically operating said pressure-applying means to apply and release the pressure during the time that the die is closed and clamped to the nozzle, automatically operated core-pulling mechanism for withdrawing cores from the die and repositioning them therein, and an ejecting mechanism operated automatically to eject the casting from the die while the cores are in the withdrawn condition.

3. A die casting machine comprising a pressure chamber for the material to be cast provided with a discharge nozzle, a movable die carrier for one part of a sectional die, a movable die carrier for another part of the sectional die, means for moving the die carriers relatively to each other and to the nozzle to close the die and clamp it to the nozzle and to hold the die for a time at the casting position and thereafter to unclamp the die from the nozzle and separate the die sections, mechanism for automatically operating said means through a complete cycle, means including a valve device for admitting a fluid under pressure into the pressure chamber to eject said material through the nozzle directly into the die and thereafter to exhaust the pressure fluid from the pressure chamber, means for automatically operating said valve device to admit pressure fluid into and exhaust it from the pressure chamber during the time that the die is closed and clamped to the nozzle, a safety valve in control of the pressure fluid to be admitted into the pressure chamber, and means for automatically operating the safety valve independently of the means for operating said valve device and in such manner that the safety valve will be open only substantially during the time that said valve device is admitting pressure fluid to the pressure chamber.

4. A die casting machine comprising a pressure chamber for the material to be cast provided with a discharge nozzle, a movable die carrier for one part of a sectional die, a movable die carrier for another part of the sectional die, means for moving the die carriers relatively to each other and to the nozzle to close the die and clamp it to the nozzle and to hold the die for a time at the casting position and thereafter to unclamp the die from the nozzle and separate the die sections, mechanism for automatically operating said means through a complete cycle, means including a valve device for admitting a fluid under pressure into the pressure chamber to eject said material through the nozzle directly into the die and thereafter to exhaust the pressure fluid from the pressure chamber, means for automatically op-

- erating said valve device to admit pressure fluid into and exhaust it from the pressure chamber during the time that the die is closed and clamped to the nozzle, a safety valve in control of the pressure fluid to be admitted into the pressure chamber, and means for automatically operating the safety valve to open it during the terminal part of the closing movement of the die and to close it during the initial part of the opening movement of the die.
5. A die casting machine comprising a pressure chamber forming a melting pot for metal to be cast and provided with a discharge nozzle, a movable die carrier for one part of a sectional die, a movable die carrier for another part of the sectional die, means for moving the die carriers relatively to each other and to the nozzle to close the die and clamp it to the nozzle and to hold the die for a time at the casting position and thereafter to unclamp the die from the nozzle and separate the die sections, mechanism for automatically operating said means through a complete cycle, means including a valve device for admitting a fluid under pressure into the pressure chamber to eject the molten metal through the nozzle directly into the die and thereafter to exhaust the pressure fluid from the pressure chamber, means for automatically operating said valve device to admit pressure fluid into and exhaust it from the pressure chamber during the time that the die is closed and clamped to the nozzle, and a metal-replenishing feed mechanism operating automatically to feed ingots to the pressure chamber while there is no pressure of pressure fluid therein.
6. A die casting machine comprising a pressure chamber forming a melting pot for metal to be cast and provided with a nozzle, a die adapted to co-operate with the nozzle to receive the molten metal therefrom, means including a valve device for admitting a fluid under pressure into the pressure chamber to eject the molten metal through the nozzle into the die and thereafter to exhaust the pressure fluid from the pressure chamber, and a metal-replenishing feed mechanism operating automatically in timed relation to said valve device to feed ingots to the pressure chamber at predetermined times while the pressure fluid is exhausted therefrom.
7. A die casting machine having, in combination, a pressure chamber for the material to be cast provided with a discharge nozzle, a first die carrier slidable to and from the nozzle to clamp a die section to the nozzle and to retract it therefrom, a second die carrier outward from the first from the nozzle and slidable toward and away from the nozzle in the same direction as but through a greater distance than the first to close and open the die, and operating means in common for said die carriers for concomitantly sliding said die carriers in the same direction and to slide the said second die carrier through a greater distance than the first, thereby to open and close the die and to clamp it to and unclamp it from the nozzle.
8. A die casting machine having, in combination, a pressure chamber for the material to be cast provided with a discharge nozzle, a first die carrier slidable to and from the nozzle to clamp a die section to the nozzle and to retract it therefrom, a second die carrier outward from the first from the nozzle and slidable toward and away from the nozzle in the same direction as but through a greater distance than the first to close and open the die, and operating means in common for said die carriers adapted to effect concomitant sliding movement of said die carriers toward and away from the nozzle and to move the second die carrier at a higher rate of speed than the first, thereby to close the die concurrently with its clamping to the nozzle and to open the die concurrently with its unclamping and retraction from the nozzle.
9. A die casting machine having, in combination, a pressure chamber for the material to be cast provided with a discharge nozzle, a first die carrier slidable to and from the nozzle to clamp a die section to the nozzle and to retract it therefrom, a second die carrier outward from the first from the nozzle and slidable toward and away from the nozzle in the same direction as but through a greater distance than the first to close and open the die, operating means for imparting sliding movement to one of the die carriers, and coupling means for causing the said sliding movement of the said one die carrier to impart sliding movement at a different rate of speed to the other die carrier in such manner that the said second die carrier moves faster than the said first die carrier.
10. A die casting machine having, in combination, a pressure chamber for the material to be cast provided with a discharge nozzle, a first die carrier slidable to and from the nozzle to clamp a die section to the nozzle and to retract it therefrom, a second die carrier outward from the first from the nozzle and slidable toward and away from the nozzle in the same direction as but through a greater distance than the first to close and open the die, operating means for imparting sliding movement to said first die carrier toward and away from the nozzle, and coupling means for causing the sliding movement of said first die carrier to impart to said second die carrier sliding movement toward and away from the nozzle at a faster speed than that of said first die carrier.

11. A die casting machine having, in combination, a pressure chamber for the material to be cast provided with a discharge nozzle, a first die carrier slidable to and from the nozzle to clamp a die section to the nozzle and to retract it therefrom, a second die carrier outward from the first from the nozzle and slidable toward and away from the nozzle in the same direction as but through a greater distance than the first to close and open the die, operating means for imparting sliding movement to said first die carrier toward and away from the nozzle, coupling means between the die carriers including toggle links, a stationary rack extending in the direction of movement of the die carriers, and a spur gear engaging the rack and connected to one of the toggle links to operate the toggle for imparting sliding movement to said second die carrier, the arrangement being such as properly to coordinate the movement of the die carriers.

12. A die casting machine having, in combination, a pressure chamber for the material to be cast provided with a discharge nozzle, a first die carrier slidable to and from the nozzle to clamp a die section to the nozzle and to retract it therefrom, a second die carrier outward from the first from the nozzle and slidable toward and away from the nozzle in the same direction as but through a greater distance than the first to close and open the die, operating means for imparting sliding movement to said first die carrier toward and away from the nozzle, coupling means between the die carriers including toggle links, a stationary rack extending in the direction of movement of the die carriers, and a spur gear engaging the rack and connected to one of the toggle links to operate the toggle for imparting sliding movement to said second die carrier, the arrangement being such as properly to coordinate the movements of the die carriers, said operating means comprising a toggle, and means for operating the toggle.

13. A die casting machine having, in combination, a pressure chamber for the material to be cast provided with a discharge nozzle, a first die carrier slidable to and from the nozzle to clamp a die section to the nozzle and to retract it therefrom, a second die carrier outward from the first from the nozzle and slidable toward and away from the nozzle in the same direction as but through a greater distance than the first to close and open the die, operating means for imparting sliding movement to said first die carrier toward and away from the nozzle, coupling means between the die carriers including toggle links, a stationary rack extending in the direction of movement of the die carriers, and a spur gear engaging the rack and connected to one of the toggle links

to operate the toggle for imparting sliding movement to said second die carrier, the arrangement being such as properly to co-ordinate the movements of the die carriers, said operating means comprising a first toggle link pivoted on a stationary part of the machine, means for turning said link on its pivot, and a second toggle link pivoted to the first and connected to said first die carrier.

14. A die casting machine having, in combination, a pressure chamber for the material to be cast provided with a discharge nozzle, a machine frame having a guideway extending away from the nozzle, a first die carrier slidable on the guideway to and from the nozzle, guide-rods secured at one end to said die carrier and extending away from the nozzle, a cross-head secured to the other ends of said guide-rods and slidably guided on said guideway, a second die carrier slidable on said guide-rods to and from the first die carrier, a stationary rack parallel with the guideway, a gear journaled on the cross-head and engaging the rack, a short toggle link connected to the gear to be turned thereby, a longer toggle link pivotally connecting the short toggle link to the second die carrier, and means for sliding the cross-head forward and back on the guideway, whereby the die will be closed and clamped to the nozzle and opened and retracted from the nozzle.

15. A die casting machine having in combination, a pressure chamber for the material to be cast provided with a discharge nozzle, a machine frame having a guideway extending away from the nozzle, a first die carrier slidable on the guideway to and from the nozzle, guide-rods secured at one end to said die carrier and extending away from the nozzle, a cross-head secured to the other ends of said guide-rods and slidably guided on said guideway, a second die carrier slidable on said guide-rods to and from the first die carrier, a stationary rack parallel with the guideway, a gear journaled on the cross-head and engaging the rack, a short toggle link connected to the gear to be turned thereby, a longer toggle link pivotally connecting the short toggle link to the second die carrier, a pivoted short toggle link, a longer toggle link pivotally connecting said pivoted short toggle link to the cross-head, and operating means for turning said pivoted short toggle link on its pivot to slide the cross-head forward and back on the guideway.

16. A die casting machine having, in combination, a pressure chamber for the material to be cast provided with a discharge nozzle, a first die carrier slidable to and from the nozzle to clamp a die section to the nozzle and to retract it therefrom, a second die carrier outward from the first from the

- nozzle and slideable toward and away from the nozzle in the same direction as but through a greater distance than the first to close and open the die, operating means 5 adapted to effect concomitant sliding movement of said die carriers toward and away from the nozzle and to move the second die carrier at a higher rate of speed than the first, thereby to close the die concurrently 10 with its clamping to the nozzle and to open the die concurrently with its unclamping and retraction from the nozzle, a core pulling and repositioning device on the second die carrier, and means connected to the first 15 die carrier for automatically operating said device to draw the cores during the opening movement of the die and to reposition the cores during the closing movement of the die. 20 17. A die casting machine having, in combination, a pressure chamber for the material to be cast provided with a discharge nozzle, a first die carrier slideable to and from the nozzle to clamp a die section to the nozzle and to re- 25 tract it therefrom, a second die carrier outward from the first from the nozzle and slideable toward and away from the nozzle and first die carrier to close and open the die, operating means for sliding the first die car- 30 rier to clamp its die section to and retract it from the nozzle, coupling means to cause the sliding of the first die carrier to slide the second die carrier at a higher speed and through a greater distance than the first die 35 carrier so as to close the die when it is clamped to the nozzle and to open the die when it is retracted from the nozzle, means for automatically operating said operating means to move the die carriers through a 40 complete cycle and providing for a die- 45 charging period of rest of the die carriers at their casting position, means including a valve device for admitting a fluid under pressure into the pressure chamber to eject said material through the nozzle directly into the die and thereafter to exhaust the pressure fluid from the pressure chamber, and means for automatically operating said valve device at the proper time to admit pressure fluid into and exhaust it from the pressure chamber during the time that the die is closed and clamped to the nozzle. 50 18. A die casting machine comprising a pressure chamber for the material to be cast provided with a discharge nozzle, a first die carrier slideable to and from the nozzle to clamp a die section to the nozzle and to re- 55 tract it therefrom, a second die carrier outward from the first from the nozzle and slideable toward and away from the nozzle and first die carrier to close and open the die, die carrier operating means for imparting concomitant sliding movement to the die carriers and adapted to move the second die carrier at a higher speed and through a greater distance than the first so as to close the die concurrently with its clamping to the nozzle and to open the die concurrently 60 with its retraction from the nozzle, means for automatically operating said operating means to move the die carriers through a complete cycle and providing for a die- 65 charging period of rest of the die carriers at their casting position, means including a valve de- 70 75 80 85 90 95 100 105 110 115 120 125 130
- valve device for admitting a fluid under pressure into the pressure chamber to eject said material through the nozzle directly into the die and thereafter to exhaust the pressure fluid from the pressure chamber, 70 and means for automatically operating said valve device at the proper time to admit pressure fluid into and exhaust it from the pressure chamber during the time that the die is closed and clamped to the nozzle. 75 19. A die casting machine comprising a pressure chamber for the material to be cast provided with a discharge nozzle, a first die carrier slideable to and from the nozzle to clamp a die section to the nozzle and to re- 80 tract it therefrom, a second die carrier outward from the first from the nozzle and slideable toward and away from the nozzle and first die carrier to close and open the die, operating means for sliding the first die car- 85 rier to clamp its die section to and retract it from the nozzle, coupling means to cause the sliding of the first die carrier to slide the second die carrier at a higher speed and through a greater distance than the first die 90 carrier so as to close the die when it is clamped to the nozzle and to open the die when it is retracted from the nozzle, means for automatically operating said operating means to move the die carriers through a 95 complete cycle and providing for a die- 100 charging period of rest of the die carriers at their casting position, means including a valve device for admitting a fluid under pressure into the pressure chamber to eject said material through the nozzle directly into the die and thereafter to exhaust the pressure fluid from the pressure chamber, and means for automatically operating said valve device at the proper time to admit pressure fluid into and exhaust it from the pressure chamber during the time that the die is closed and clamped to the nozzle. 105 20. A die casting machine comprising a pressure chamber for the material to be cast provided with a discharge nozzle, a first die carrier slideable to and from the nozzle to clamp a die section to the nozzle and to re- 110 tract it therefrom, a second die carrier outward from the first from the nozzle and slideable toward and away from the nozzle and first die carrier to close and open the die, die carrier operating means for imparting concomitant sliding movement to the die carriers and adapted to move the second die carrier at a higher speed and through a greater distance than the first so as to close the die concurrently with its clamping to the nozzle and to open the die concurrently with its retraction from the nozzle, means for au- 115 tomatically operating said operating means to move the die carriers through a complete cycle and providing for a die-charging period of rest of the die carriers at their casting position, means including a valve de- 120 125 130

vice for admitting a fluid under pressure into the pressure chamber to eject said material through the nozzle directly into the die and thereafter to exhaust the pressure fluid from the pressure chamber, means for automatically operating said valve device at the proper time to admit pressure fluid into and exhaust it from the pressure chamber during the time that the die is closed 5 and clamped to the nozzle, a core pulling and repositioning device on the second die carrier, and means connected to the first die carrier for automatically operating said device to draw the cores during the opening 10 movement of the die and to reposition the cores during the closing movement of the die.

21. A die casting machine comprising a pressure chamber for the material to be cast 20 provided with a discharge nozzle, a first die carrier slidable to and from the nozzle to clamp a die section to the nozzle and to retract it therefrom, a second die carrier outward from the first from the nozzle and 25 slidable toward and away from the nozzle and first die carrier to close and open the die, die carrier operating means for imparting concomitant sliding movement to the die carriers and adapted to move the second die carrier at a higher speed and through a 30 greater distance than the first so as to close the die concurrently with its clamping to the nozzle and to open the die concurrently with its retraction from the nozzle, means for automatically operating said operating means 35 to move the die carriers through a complete cycle and providing for a die-charging period of rest of the die carriers at their casting position, means including a valve device 40 for admitting a fluid under pressure into the pressure chamber to eject said material through the nozzle directly into the die and thereafter to exhaust the pressure fluid from the pressure chamber, means for automatically operating said valve device at the proper time to admit pressure fluid into and exhaust it from the pressure chamber 45 during the time that the die is closed and clamped to the nozzle, a core pulling and repositioning device on the second die carrier, means connected to the first die carrier for automatically operating said device to draw the cores during 50 the opening movement of the die and to reposition the cores during the closing movement of the die, a casting-ejecting device on the second die carrier, and means connected to the first die carrier for automatically operating the casting-ejecting device to eject the 55 casting during the final part of the die-opening movement of the second die carrier and after the cores have been withdrawn.

60 22. A die casting machine comprising a pressure chamber for the material to be cast 65 provided with a discharge nozzle, a machine

frame having a guideway extending away from the nozzle, a first die carrier slidable on the guideway to and from the nozzle, guide-rods secured at one end to said die carrier and extending away from the nozzle, a cross-head secured to the other ends of said guide-rods and slidably guided on said guideway, a second die carrier slidable on said guide-rods to and from the first die carrier, means for transmitting sliding movement from the cross-head to the second die carrier at a multiplied rate and in the same direction for closing the die as the die carriers slide towards the nozzle and for opening the die as the die carriers slide away from the nozzle, automatically acting mechanism to slide the cross-head forward and back to close the die and clamp it to the nozzle and to open the die and retract it from the nozzle and adapted to provide a die-charging period of rest of the die at its casting position, automatically operated means for forcing the material to be cast from the pressure chamber through the nozzle directly into the closed die, a rack carried by the cross-head, and a core-pulling device carried by the second die carrier and having a gear engaged and operated by the rack.

23. A die casting machine comprising a pressure chamber for the material to be cast 95 provided with a discharge nozzle, a machine frame having a guideway extending away from the nozzle, a first die carrier slidable on the guideway to and from the nozzle, guide-rods secured at one end to said die carrier 100 and extending away from the nozzle, a cross-head secured to the other ends of said guide-rods and slidably guided on said guideway, a second die carrier slidable on said guide-rods to and from the first die carrier, means for transmitting sliding movement from the cross-head to the second die carrier at a multiplied rate and in the same direction for closing the die as the die carriers slide towards the nozzle and for opening the die 110 as the die carriers slide away from the nozzle, automatically acting mechanism to slide the cross-head forward and back to close the die and clamp it to the nozzle and to open the die and retract it from the nozzle and adapted to provide a die-charging period of rest of the die at its casting position, automatically operated means for forcing the material to be cast from the pressure chamber through the nozzle directly into the closed die, a rack carried by the cross-head, and a casting-ejecting device carried by the second die carrier and having a gear engaged and operated by the rack.

24. A die casting machine having, in combination, a pressure chamber for the material to be cast provided with a discharge nozzle, die carriers movable relatively to the nozzle and to each other, means adapted to move one of said die carriers upon movement of

- the other and whereby the die will be closed and clamped to the nozzle upon movement of said other die carrier in one direction and will be opened and retracted from the nozzle upon movement of said other die carrier in the opposite direction, and automatically acting mechanism adapted to move said other die carrier first to close the die and clamp it to the nozzle and thereafter to open the die and retract it from the nozzle, and said mechanism also being adapted to provide a die-charging period of rest of the die in the casting position.
25. A die casting machine comprising a pressure chamber for the material to be cast provided with a discharge nozzle, die carriers movable relatively to the nozzle and to each other, means adapted to move one of said die carriers upon movement of the other and whereby the die will be closed and clamped to the nozzle upon movement of said other die carrier in one direction and will be opened and retracted from the nozzle upon movement of said other die carrier in the opposite direction, automatically acting mechanism adapted to move said other die carrier first to close the die and clamp it to the nozzle and thereafter to open the die and retract it from the nozzle, and said mechanism also being adapted to provide a die-charging period of rest of the die in the casting position, and means controlled by said mechanism to operate automatically for forcing the material to be cast from the pressure chamber through the nozzle directly into the die at its casting position.
26. A die casting machine having, in combination, a pressure chamber for the material to be cast provided with a discharge nozzle, die carriers movable relatively to the nozzle and to each other, a die-carrier-operating member slidable in a forward direction to close the die and clamp it to the nozzle in casting position and slidable in the reverse direction to open the die and retract it from the nozzle, and automatically acting mechanism for sliding said member first in the forward direction and then in the reverse direction and adapted to provide a die-charging period of rest of the die at its casting position.
27. A die casting machine having, in combination, a pressure chamber for the material to be cast provided with a discharge nozzle, die carriers movable relatively to the nozzle and to each other, a die-carrier-operating member slidable in a forward direction to close the die and clamp it to the nozzle in casting position and slidable in the reverse direction to open the die and retract it from the nozzle, and automatically acting mechanism for sliding said member first in the forward direction and then in the reverse direction and adapted to provide a die-charging period of rest of the die at its casting position, said mechanism comprising a casting position, said mechanism comprising a rotative driving part, reversing gearing, means for automatically reversing said gearing, and a reversible shaft driven from said part through said reversing gearing first in a forward direction and then in the reverse direction, and operating connections from said reversible shaft to said member.
28. A die casting machine having, in combination, a pressure chamber for the material to be cast provided with a discharge nozzle, die carriers movable relatively to the nozzle and to each other, a die-carrier-operating member slidable in a forward direction to close the die and clamp it to the nozzle in casting position and slidable in the reverse direction to open the die and retract it from the nozzle, and automatically acting mechanism for sliding said member first in the forward direction and then in the reverse direction and adapted to provide a die-charging period of rest of the die at its casting position, said mechanism comprising a rotative driving part, reversing gearing, means for automatically reversing said gearing, a reversible shaft driven from said part through said reversing gearing first in a forward direction and then in the reverse direction, a rock shaft transverse to the path of movement of said member, gearing connecting said reversible shaft to said rock shaft, and a pair of toggle links pivoted together and one of which is fixed on said rock shaft and the other of which is pivoted to said member.
29. A die casting machine having, in combination, a pressure chamber for the material to be cast provided with a discharge nozzle, die carriers movable relatively to the nozzle and to each other, a die-carrier-operating member slidable in a forward direction to close the die and clamp it to the nozzle in casting position and slidable in the reverse direction to open the die and retract it from the nozzle, and automatically acting mechanism for sliding said member first in the forward direction and then in the reverse direction and adapted to provide a die-charging period of rest of the die at its casting position, said mechanism comprising a rotative driving part, a reversible shaft, operating connections from said reversible shaft to said member, reversing gearing for connecting said driving part to said reversible shaft and including a reversing clutch having an element shiftable to and adapted to occupy a forward-drive position or an intermediate non-driving neutral position or a reverse-drive position, a clutch shifter engaging said element and shiftable to corresponding positions, a tappet moved by said slide member to engage and shift said clutch shifter from the forward-drive position to the neutral position during the final part of the forward movement of said mem-

- ber in which the die has been closed and clamped to the nozzle, a device controlled by said member to be operated by said driving part to shift the clutch shifter from neutral 5 to reverse position after the material to be cast has been forced into the die, and a second tappet moved by said slidable member to engage and shift said clutch shifter from its reverse position to its neutral position 10 during the reverse movement of said member after the die has been opened and unclamped from the nozzle.
30. A die casting machine comprising a pressure chamber provided with a discharge nozzle, die carriers movable relatively to the nozzle and to each other, a die-carrier-operating member slidable forward to close the die and clamp it to the nozzle in casting position and slidable backward to open the 15 die and retract it from the nozzle, means for forcing the material to be cast from the pressure chamber through the nozzle directly into the die, and automatically acting mechanism to operate said means while the die is in casting position and to slide said member forward and backward and providing a die-charging period of rest of the die at its casting position.
31. A die casting machine, comprising a pressure chamber provided with a discharge nozzle, die carriers movable relatively to the nozzle and to each other, a die-carrier-operating member slidable forward to close the die and clamp it to the nozzle in casting 20 position and slidable backward to open the die and retract it from the nozzle, means including a valve device operable to admit a fluid under pressure into the pressure chamber to eject said material through the nozzle directly into the die and thereafter to exhaust the pressure fluid from the pressure chamber, and automatically acting mechanism to operate said valve device while the die is in the casting position and for 25 sliding said member forward and backward and adapted to provide a die-charging period of rest of the die at its casting position, said mechanism comprising a rock shaft transverse to the path of movement of said slidable member, a pair of toggle links pivoted together and one of which is fixed on said rock shaft and the other of which is pivoted to said slidable member, a reversible shaft, worm gearing connecting said reversible shaft to said rock shaft, a rotative main driving shaft, reversing gearing for connecting said driving shaft to said reversible shaft and including a reversing clutch having an element shiftable to and adapted to occupy a forward-drive position or an intermediate non-driving neutral position or a reverse-drive position, a clutch shifter engaging said element and shiftable to corresponding positions, a controlling rod carried by said slidable member, a tappet carried by the controlling rod to shift the clutch shifter from its forward-drive position to its 30
32. A die casting machine comprising a pressure chamber provided with a discharge nozzle, die carriers movable relatively to the nozzle and to each other, a die-carrier-operating member slidable forward to close the die and clamp it to the nozzle in casting position and slidable backward to open the die and retract it from the nozzle, means for forcing the material to be cast from the pressure chamber through the nozzle directly into the die, and automatically acting mechanism to operate said means while the die is in casting position and to slide said member forward and backward and providing a die-charging period of rest of the die at its casting position, said mechanism comprising a rotative driving part, a reversible 35

- neutral position during the final part of the movement of the die to casting position, a one-revolution clutch geared to the main shaft, a clutch-controlling finger carried by 5 the controlling rod to set the one-revolution clutch in operation during the final part of the movement of the die to casting position, a cam device operated by the one-revolution clutch to operate said valve device to admit 10 pressure fluid to the pressure chamber and exhaust it therefrom while the die is held at rest in the casting position, a second cam device operated by the one-revolution clutch to shift the clutch shifter from its neutral to 15 its reverse-drive position after the pressure fluid has been exhausted from the pressure chamber, and a second tappet carried by the controlling rod to shift the clutch shifter from reverse-drive to neutral position after 20 the die has been opened and unclamped from the nozzle.

34. A die casting machine having, in combination, a pressure chamber for the material to be cast provided with a discharge 25 nozzle, a machine frame having a guideway extending away from the nozzle, a first die carrier slidable on the guideway to and from the nozzle, guide-rods secured at one end to said die carrier and extending away 30 from the nozzle, a cross-head secured to the other ends of said guide-rods and slidably guided on said guideway, a second die carrier slidable on said guide-rods to and from the first die carrier, a pair of toggle links 35 pivoted together and one of which is pivoted to the cross-head and the other of which is pivoted to said second die carrier, means to operate the toggle links upon sliding movement of the cross-head, and operating means 40 for imparting sliding movement to the cross-head, said operating means comprising a second pair of toggle links pivoted together and one of which is pivoted on a stationary part of the machine and the other of which is pivoted to the cross-head, and means for 45 operating said second pair of toggle links.

35. A die casting machine having, in combination, a pressure chamber for the material to be cast provided with a discharge 50 nozzle, a machine frame having a guideway extending away from the nozzle, a first die carrier slidable on the guideway to and from the nozzle, guide-rods secured at one end to said die carrier and extending away from the 55 nozzle, a cross-head secured to the other ends of said guide-rods and slidably guided on said guideway, a second die carrier slidable on said guide-rods to and from the first die carrier, a rock shaft journaled on the cross-head transverse to its path of movement, a pair of toggle links pivoted together and one of which is fixed on the rock shaft and the other of which is pivoted to the second die carrier, means to rock the rock shaft 60 upon sliding movement of the cross-head, 65 and operating means for imparting sliding movement to the cross-head, said operating means comprising a second rock shaft journaled on a stationary part of the machine transverse to the path of movement 70 of the cross-head a second pair of toggle links pivoted together and one of which is fixed on the second rock shaft and the other of which is pivoted to the cross-head, and means for rocking the second rock shaft. 75

36. A die casting machine comprising a pressure chamber for the material to be cast provided with a discharge nozzle, a machine frame having a guideway extending away from the nozzle, a first die carrier slidable on the guideway to and from the nozzle, guide-rods secured at one end to said die carrier and extending away from the nozzle, a cross-head secured to the other ends of said guide-rods and slidably guided on said guideway, a second die carrier slidable on said guide-rods to and from the first die carrier, a pair of toggle links pivoted together and one of which is pivoted to the cross-head and the other of which is pivoted to said second die carrier, means to operate the toggle links upon sliding movement of the cross-head, a second pair of toggle links pivoted together and one of which is pivoted on a stationary part of the machine and the other of which is pivoted to the cross-head, pressure-applying means for forcing the material to be cast from the pressure chamber through the nozzle directly into the die, and mechanism acting automatically to operate the second pair of toggle links and the pressure-applying means, and being adapted to move the die to the casting position and hold it there while the material is forced into the die, and to operate the pressure-applying means to apply and release the pressure while the die is at the casting position. 100

37. A die casting machine comprising a pressure chamber provided with a discharge nozzle, die carriers movable relatively to the nozzle and to each other for moving a sectional die to and from the casting position, means for automatically moving the die carriers through a complete cycle to and from the casting position and adapted to provide a die-charging period of rest of the die sections at the casting position, and means controlled by the movement of the die carriers for automatically forcing the material to be cast from the pressure chamber through the nozzle into the die while the latter is at the casting position. 110

38. A die casting machine comprising a pressure chamber provided with a discharge nozzle, die carriers movable relatively to the nozzle and to each other for moving a sectional die to and from the casting position, means for automatically moving the die carriers through a complete cycle to and from the casting position and adapted to provide 125

a die-charging period of rest of the die sections at the casting position and fluid pressure means controlled by the movement of the die carriers for automatically forcing the material to be cast from the pressure chamber through the nozzle into the die while the latter is at the casting position.

39. A die casting machine comprising a pressure chamber provided with a discharge nozzle, die carriers movable relatively to the nozzle and to each other for moving a sectional die to and from the casting position, means for automatically moving the die carriers through a complete cycle to and from the casting position and adapted to provide a die-charging period of rest of the die sections at the casting position, means including a valve device for admitting a fluid under pressure into the pressure chamber to eject said material from the pressure chamber through the nozzle into the die, and means controlled by the movement of the die carriers for automatically operating said valve device to admit pressure fluid into and exhaust it from the pressure chamber while the die is at the casting position.

40. A die casting machine comprising a pressure chamber provided with a discharge nozzle, die carriers movable relatively to the nozzle and to each other for moving a sectional die to and from the casting position, a power-driven rotative part, means operated by said part for automatically moving the die carriers through a complete cycle to and from the casting position and adapted to provide a die-charging period of rest of the die sections at the casting position, and means operated by said part and controlled by the movement of the die carriers for automatically forcing the material to be cast from the pressure chamber through the nozzle into the die while the latter is at the casting position.

41. A die casting machine comprising a pressure chamber provided with a discharge nozzle, die carriers movable relatively to the nozzle and to each other for moving a sectional die to and from the casting position, a power-driven rotative part, means operated by said part for automatically moving the die carriers through a complete cycle to and from the casting position and adapted to provide a die-charging period of rest of the die sections at the casting position, means including a valve device for admitting a fluid under pressure into the pressure chamber to eject said material from the pressure chamber through the nozzle into the die, and means operated by said part and controlled by the movement of the die carriers for automatically operating said valve device to admit pressure fluid into and exhaust it from the pressure chamber while the die is at the casting position.

42. A die casting machine comprising a

pressure chamber forming a melting pot for metal to be cast and provided with a discharge nozzle, die carriers movable relatively to the nozzle and to each other for moving a sectional die to and from the casting position, means for automatically moving the die carriers through a complete cycle to and from the casting position and adapted to provide a die-charging period of rest of the die sections at the casting position, means including a valve device for admitting a fluid under pressure into the pressure chamber to eject said material from the pressure chamber through the nozzle into the die, means controlled by the movement of the die carriers for automatically operating said valve device to admit pressure fluid into and exhaust it from the pressure chamber while the die is at the casting position, and a metal-replenishing feed device operated automatically in timed relation to the operation of said valve device to feed ingots to the pressure chamber at times while the pressure fluid is exhausted therefrom.

43. A die casting machine comprising a pressure chamber forming a melting pot for metal to be cast and provided with a discharge nozzle, die carriers movable relatively to the nozzle and to each other for moving a sectional die to and from the casting position, a power-driven rotative part, means operated by said part for automatically moving the die carriers through a complete cycle to and from the casting position and adapted to provide a die-charging period of rest of the die sections at the casting position, means including a valve device for admitting a fluid under pressure into the pressure chamber to eject said material from the pressure chamber through the nozzle into the die, means operated by said part and controlled by the movement of the die carriers for automatically operating said valve device to admit pressure fluid into and exhaust it from the pressure chamber while the die is at the casting position, and a metal-replenishing feed mechanism caused to operate automatically by the movement of a die carrier to feed ingots to the pressure chamber at times while the pressure fluid is exhausted therefrom and including a controlling device adapted to be manipulated so as to vary the frequency of the ingot-feeding operations relatively to the casting operations as desired.

44. A die casting machine comprising a pressure chamber provided with a discharge nozzle, die carriers movable relatively to the nozzle and to each other for moving a sectional die to and from the casting position, means for automatically moving the die carriers through a complete cycle to and from the casting position and adapted to provide a die-charging period of rest of the die sections at the casting position, means con-

- trolled by the movement of the die carriers for automatically forcing the material to be cast from the pressure chamber through the nozzle into the die while the latter is at the casting position, and a core-pulling device on one of the die carriers adapted to be automatically operated by the die carriers in their relative movement as they move away from the casting position.
- 10 45. A die casting machine comprising a pressure chamber provided with a discharge nozzle, die carriers movable relatively to the nozzle and to each other for moving a sectional die to and from the casting position, means for automatically moving the die carriers through a complete cycle to and from the casting position and adapted to provide a die-charging period of rest of the die sections at the casting position, means controlled by the movement of the die carriers for automatically forcing the material to be cast from the pressure chamber through the nozzle into the die while the latter is at the casting position, and a casting-ejecting device on one of the die carriers adapted to be automatically operated by the die carriers in their relative movement as they move away from the casting position.
46. A die casting machine comprising a pressure chamber forming a melting pot for metal to be cast and provided with a discharge nozzle, die carriers movable relatively to the nozzle and to each other for moving a sectional die to and from the casting position, a power-driven rotative part, means operated by said part for automatically moving the die carriers through a complete cycle to and from the casting position and adapted to provide a die-charging period of rest of the die sections at the casting position, means including a valve device for admitting a fluid under pressure into the pressure chamber to eject said material from the pressure chamber through the nozzle into the die, means operated by said part and controlled by the movement of the die carriers for automatically operating said valve device to admit pressure fluid into and exhaust it from the pressure chamber while the die is at the casting position, a metal-replenishing feed mechanism which by the movement of a die carrier is caused to operate automatically in timed relation to the operation of said valve device to feed ingots to the pressure chamber after the pressure fluid has been exhausted therefrom and at desired predetermined intervals relative to the casting operations, a core-pulling device adapted to be operated automatically by the die carriers in their relative movement as they move away from the casting position, and a casting-ejecting device on the same die carrier as the core-pulling device and adapted to be operated automatically by the die carriers in their relative movement as they move away from the casting position to eject the casting after the pulling of the cores.
